UNITED STATES PATENT OFFICE.

WALTER WRIGHT, OF SAN FRANCISCO, CALIFORNIA, ASSIGNOR, BY MESNE ASSIGNMENTS, TO UNDERWOOD COMPUTING MACHINE COMPANY, A CORPORATION OF NEW YORK.

COMPUTING ATTACHMENT FOR TYPE-WRITERS.

1,162,730.

Specification of Letters Patent.

Patented Nov. 30, 1915.

Application filed January 17, 1908. Serial No. 411,245.

To all whom it may concern:

Be it known that I, WALTER WRIGHT, a citizen of Great Britain, residing at San Francisco, in the county of San Francisco 5 and State of California, have invented new and useful Improvements in Computing Attachments for Type-Writers, of which the following is a specification.

One of the objects of the present invention is to improve the means whereby the number of digit wheels are driven by a source of power controlled by the numeral keys. I connect the master wheel (or digit-wheel actuator) to the source of power, 10 which may be in the form of a motor, preferably an electric motor. The master wheel is also connected to a device whereby its movements are determined or controlled, the controller being in the nature of an 15 index-wheel that is controlled by the numeral keys; the index-wheel having a circular series of settable pins, bolts or other indexing devices, which, by means of said keys, may be set or projected from the 20 wheel, and then employed to limit the stroke of the index wheel and the master wheel. The index pins are normally stationary, and in register with a circular series of jacks or 25 setting devices, which are mounted upon the 30 machine frame and connected to the numeral keys, whereby any key may set the necessary index pin on said index-wheel. The pin, after it is set, may coöperate in 35 any suitable way with other devices to limit the stroke of the index-wheel. The coöperating mechanism illustrated herein comprises a pinion which is driven by the projected index-pin, and an escapement device which is connected to said pinion; the 40 escapement device being also under the control of said numeral keys. Hence when any key is depressed, a corresponding index pin is projected, and at the same time the pinion is released, and hence the motor is permitted 45 to turn the index-wheel until the projected pin strikes the pinion, whereby it is arrested. The master wheel, of course, turns correspondingly with the index-wheel.

The escapement mechanism preferably 50 comprises a large diameter escapement wheel connected with the pinion, and suitable escapement dogs or pawls to control the

movements of the escapement wheel. A universal bar controls said escapement dogs or pawls, and is itself connected to be operated by any of the numeral keys. Said index-wheel and said escapement wheel may be regarded as having the relation of primary and secondary escapement wheels; since the dogs let off the secondary escapement wheel, and since the latter lets off the index-wheel, at the key strokes.

In using the improvements in a type-writing machine, the indexing mechanism may be placed at one side of the machine, 65 and connections may extend up from the keys and transversely over the key levers to said indexing mechanism, thus making the machine compact, and adapting the improvements to be applied readily to existing 70 types of typewriting machines.

The motor may be connected in various ways, but is herein illustrated as running continuously and as having a slip-connection to the computing mechanism, whereby 75 the latter may be under constant torque. The action of the computing mechanism is therefore very prompt. The resistance of the numeral keys to the touch of the operator is very light.

When it is desired to write figures in the computing zone without operating the computing mechanism, the connections which extend from the keys to the indexing mechanism may be disconnected. This may be 85 done by pressing down a silencing key; and a separate key is provided for restoring the connection. It is usual in typewriting machines to provide a case-shift mechanism, which enables other characters to be printed 90 than numerals; and said case-shift mechanism is connected up by improved means, to release the several key connections whenever the numeral types are not to be printed.

Another feature of the present improvements consists broadly in provision, in a machine in which the digit wheels are rotated one after another at the striking of the keys, of means operated by the digit wheels for initiating the carry-over operation of each wheel to the next higher wheel, and a driver or means distinct from the digit wheels themselves for completing the carry-over operation, or at least for assist-

ing or boosting the carry-over devices; this driver being preferably connected to be driven by a separate source of power from the keys themselves, and, in the present instance, being connected to be rotated directly by said motor independently of said slip connection, so as always to be ready to take part in the carry-over operation, and to operate after the conclusion of the movement of the initiating digit-wheel. The driver in the present instance is illustrated in the form of a soft rubber or yielding roll, which extends along a row of carry-over pinions, the latter being normally out of engagement with this driver roll, but movable into engagement therewith by the rotation of the associated digit wheel from "9" to "0".

There is illustrated in the present instance, a multiple-length adding head or totalizer, of the type shown in the patent granted to me, No. 1,095,060, April 28, 1914. This computing head is herein divided up by partitions into groups, means being provided to extend through the partitions to enable carry-over operations to be performed between the wheels which adjoin the partitions. Each group of three wheels is divided by a regular typewriting space from, and yet operatively connected with and capable of transferring accumulations of the tens (or carry-over) to the first wheel of the next group of three counting wheels to the left; and this principle is employed throughout for the full length of the writing line or width of the typewriter carriage, where the multiple-length computing head or totalizer is of such dimensions. The invention, however, is not limited, as to certain of its features, to use of a multiple-length totalizer. It is not always necessary that the main totalizing means should comprise an array of digit wheels all of which are connected up by a continuous train of carry-over mechanism, since it is known that a series of columns written side by side can be added by means of groups of digit wheels, which groups need not be inter-connected.

The master wheel is shown as mounted on a tubular support, through which extends the master wheel shaft itself; and the digit wheels are preferably mounted directly on said tubular support, to slide therealong as the typewriter carriage travels.

Provision is made to enable said motor, which preferably rotates always in the same direction, to drive the master wheel in opposite directions, as well as the carry-over driver. Hence the totalizer may be re-set to zero by the act of writing the total on the work-sheet.

Another feature of the present invention resides in the provision of means for effecting cross-computation. For this purpose an

additional totalizer is provided, in which can be accumulated the numbers that are run into various portions of the main totalizer mechanism. In other words, while columns that are written side by side on a work-sheet are being added by the main computing means provided for that purpose, the sum of the numbers appearing in the various columns on each successive typewriting line may be added up by the cross-computer. This is shown as a separate totalizer, connected to the vertical adding means, and operated in this instance by a succession of master wheels placed at desired intervals along the run of the carriage, to correspond with the positioning of the written columns on the work-sheet. These cross-adding master wheels are all carried by a shaft which is inclosed in tubular sections, the latter serving as spacers for the master wheels. As explained in said patent, the multiple-length totalizer may be split up in various ways at various parts thereof, and, according to the present invention, cross-computation may be performed in connection with the addition of columns on the main totalizer so split up. The machine will compute and retain the totals of each and all of the columns, limited in number only by the width of said columns and the length of the writing line for which the writing machine is equipped, besides computing and registering automatically cross-footings or cross totals.

Preferably the cross-computing totalizer is placed in a tandem arrangement with respect to the main totalizer, the wheels of one totalizer thus preferably having an edge-to-edge arrangement with respect to the wheels of the other totalizer, as distinguished from the side-by-side arrangement which they would have if the totalizers were coaxial. The master wheel shafts accordingly have the arrangement of main and counter shafts, and they are connected by a common driver. Provision is made for causing either master wheel either to add, subtract, or be neutral, while the other master wheel is either adding, subtracting, or neutral, thus permitting a wide range of work to be performed. This is preferably done by a shiftable device which is arranged between the master wheel shafts; and the main drive shaft preferably turns always in the same direction. The shiftable device for each of the totalizers is shifted by means of a handle which also controls the direction of rotation of the separate power-driven driver for the carry-over operations. After the mechanisms are adjusted for simultaneous addition and subtraction, or for addition on one totalizer while the other remains neutral, it is feasible to silence the computing mechanism without disturbing such adjustment.

Other features and advantages will hereinafter appear; and certain of the improvements may be applied to other machines than combined typewriting and computing machines.

Certain features herein claimed are disclosed in my co-pending application No. 388,766, filed August 16, 1907. The claims in the present application are sufficiently broad to cover said features; but the claims in said co-pending application will be limited to features not specifically disclosed in this application.

In the accompanying drawing Figure 1 is a front view, partly in section, of a typewriting machine equipped with my invention; Fig. 2 is a broken top plan view of the numeral keys; Fig. 3 is a broken sectional view showing the computing or master wheel shaft; Fig. 4 is a similar view showing the upper transfer or tens-carrying assisting shaft; Fig. 5 is a similar view showing the lower or horizontal computing or master wheel shaft; Fig. 6 is a detail perspective view of one of the sleeves on the latter; Fig. 7 is a broken perspective view showing the key connections; Fig. 8 is a longitudinal sectional view of the controlling mechanism; Fig. 9 is a sectional view at right angles to Fig. 8; Fig. 10 is a broken perspective view of the same; Fig. 11 is a part-sectional elevation of the index-wheel and pinion; Fig. 12 is an enlarged vertical section of the computing carriage; Fig. 13 is a sectional view of the lower portion of said carriage, looking from the opposite direction to that of Fig. 12; Fig. 14 is a broken front view of the upper portion of the carriage; Fig. 15 is a perspective view of a computing wheel; Fig. 16 is a sectional view of the third computing wheel of a group; Fig. 17 is a perspective view of a transfer wheel; Fig. 18 is a similar view of the third transfer wheel of a group; Fig. 19 is a similar view of an auxiliary transfer wheel; Fig. 20 is a vertical section of the upper portion of the carriage, showing a modification of the third wheel; Fig. 21 is a perspective view of a modified form of a third transfer wheel; Fig. 22 is a side view of the machine equipped with my invention; Fig. 23 is a horizontal section of a portion thereof; Fig. 24 is a horizontal section of the reversing mechanism; Fig. 25 is a vertical section of the same; Fig. 26 is a view similar to Fig. 24 of the reversing mechanism for the transfer shaft; Fig. 27 is a sectional view of a detail of the reversing mechanism.

Attachment.—The drawings show the invention as applied to an "Underwood" typewriting machine, but it is to be understood that, with suitable changes, it may be applied to a typewriting machine of any standard construction, and also that the invention may be embodied in the form of a comput-

ing machine complete in itself, and not attached to a typewriting machine.

Key connections.—Secured to the frame 1 of the typewriting machine is a vertical plate 2, extending longitudinally of the machine over the key levers 3 (Fig. 1); and, secured upon the front of said plate 2, are guides 4 for a slide bar 5, Figs. 1 and 7 one end of which is formed with two notches 6, into either of which can spring a bent spring 7 arm 7, thereby yieldingly maintaining said bar in either of two positions. The longitudinal movement of this bar, in the manner to be presently described, simultaneously connects all the numeral key levers with the computing mechanism. To move said bar longitudinally, its other end is formed with a recess 8, into which extends an arm 9 on a rock shaft 10, (Fig. 7) to which is secured a double bell crank lever 11, to one end of which is connected a hanger hook 12 which normally enters a hole in a collar 14 on the lever 15 of the shift key 16 of the machine. The machine shown is what is known as a "shift key" machine, in which each type bar carries two type, of which one prints normally and the other only when the shift key is depressed. In said Underwood machine said shift key 16, when depressed, elevates the platen frame 16^a, to enable the capital types to print. All of the nine digits are arranged in the typewriting machine to correspond to what is known as the "lower case" characters of the top row of keys 3, so that they may be printed by said keys without using the shift key. Since some other character than a numeral is also carried on each numeral type bar, therefore, if the shift key is used, and a numeral key operated, said other character is then printed. It is therefore desirable at that time to throw the computing mechanism out of action. Upon depressing the shift key 16, the slide bar 5 is evidently moved to the right, and, as will presently appear, this has the effect of automatically disconnecting the numeral key levers from any part of the computing mechanism, so that when any numeral key is used for the purpose of writing an "upper case" character this is always done without the actuation of the computing mechanism. By the return of the shift key, said slide bar 5 is moved to the left, which then again connects the computing mechanism with the numeral keys, so that when any one of them is depressed the computing mechanism will be actuated. Through apertures 17 in said slide bar 5 pass links 18, one for each numeral key, having hook-shaped lower ends adapted by the movement of said bar to be moved into or out of engagement with apertured collars 19 secured upon the levers 3 of the nine numeral keys. Each link 18 is connected at its upper end to a bell crank lever 21, another arm of

which is connected to a wire rod 22, all of said nine connecting rods 22 passing through a ring 23 (Figs. 8 and 9), secured to the plate 2, said rods being connected respectively to blocks 24 connected to levers 25 pivotally supported by said ring 23. Thus, upon depressing any one of the numeral keys, the outer end of the corresponding lever 25 is moved to the right. The object 10 of this arrangement is to selectively control the action of the computing apparatus, hereinafter described.

In order to operate the numeral keys without actuating the computing mechanism, 15 when desired, there is provided an "Out" key 26, (Figs. 1 and 7), the stem of which key is connected to a bell crank lever 27, loose on the rock shaft 10, and having secured thereto a spring 28 adapted to engage 20 an abutment 29 extending from a depending arm of the bell crank lever 11.

A link 30 is connected to the lever 27 and to the hanger bar 12, so that the first movement of said lever 27 has the effect of without 25 drawing the hook 12 out of the hole in the collar on the shift key lever. As this takes place, the spring 28 is compressed between the lever 27 and the abutment 29. When 30 said spring can no longer yield, the lever 27, acting against the abutment 29, causes the rock shaft 10 to rock, so that the slide bar 5 is moved to the right, against the action of the retaining spring 7, which then drops into the left one of the two notches 6, 35 so that the operation of the shift key has now no effect whatever upon the connecting or disconnecting of the numeral keys with the computing mechanism. To render the key connections again operative, there is 40 provided an "in" key 31, the stem of which is connected to the lever 11, so that the depression of said key 31 moves the slide bar 5 to the left. The spring 28 then restores the key 26 to its normal position, so that the 45 hook 12 again enters the hole of the collar 14 on the shift key lever.

In order that the end of the hanger-hook 12 may at no time be permitted to hook under the collar 14, the collar 14 is illustrated 50 in Fig. 7 as extending downwardly to a point somewhat below the lower end of the vertical stroke of said hooked end.

The hooks on the links 18 are guided in their movement longitudinally of the apparatus, by their bearings in apertures 17 55 in the slide bar 5, which slides in guides 4 fixed to the fixed plate 2.

The hanger hook 12 may be prevented 60 from swinging forwardly and rearwardly of the machine, by suitable forms of connections at its junction with bell-crank 11 and link 30 and by suitable connections between link 30 and bell-crank 27, so that the hooked end of the hanger-hook 12 will always be in 65 the proper vertical plane (longitudinally of

the machine) to enter the aperture in the collar 14; or, if preferred, a suitable bracket 12^a (Figs. 1 and 7) may be provided for keeping the hanger-hook 12 in this plane.

Inasmuch as numeral keys are arranged 70 in an ordinary typewriter to cause the writing of not only numerals, but also characters other than numerals, shifting means being provided for determining what characters are to be written at the actuation of the 75 numeral keys, I have also provided the described devices, to be controlled by said shifting mechanism, for automatically disconnecting the computing mechanism from the numeral keys, to enable the latter to 80 write characters other than numerals without actuating the indexing or valuating mechanism. Moreover, when the "Out" key 26 is employed for disconnecting the computing mechanism from the numeral keys, 85 the case-shifting means is also disconnected from the computing mechanism; and it will be seen that the disconnection of the computing mechanism from the numeral keys need not occur until the computing mechanism 90 has been disconnected from the case-shifting means. This is done by the described yielding device. The case-shift key, when disconnected, may be freely operated without liability of connecting the computing mechanism to the numeral keys. The spring 7 is arranged to oppose the movement 95 of the independent controlling device 5 away from either of its limiting positions; said spring maintaining temporarily either 100 the connection or the disconnection. It will be noted that the invention includes power mechanism for operating the computing or registering mechanism, means operable by the keys and including the universal bar 51 105 operable by every numeral key, for governing said power mechanism, and means for breaking and restoring the connections between the keys and said universal bar 51.

Controller.—Secured on the right hand 110 side of the frame of the typewriting machine is a bracket 33, Fig. 1, supporting a vertical plate 34, carrying posts 35, supporting a guide plate 36, having a circular series of holes, through which extend the ends 115 of nine pusher rods 37, Figs. 8 and 9 pivotally attached to the several bell crank levers 25. Having its bearing in the plate 34 is a shaft 38, of a controller 39, which, as will be presently described, is under constant rotational pressure. Stop bolts 40, of which there should be not less than ten, slide in a circular series of slideways 41 in said controller, which slideways register with the pusher rods, and said bolts project to the 120 left of said controller normally, and until they are displaced by the action of the pusher rods 37. An annular coiled spring 42, which surrounds the controller in a groove therein deep enough to intersect the 125 130

slideways for the bolts, and which is adapted to engage one or the other of two grooves 43 formed in each bolt, yieldingly maintains the bolts in the positions to which they have been moved. When any numeral key 5 has been operated, and the corresponding pusher rod moved through the guide plate, its end impinges upon the end of a stop bolt 10 projecting from the left hand side of the controller and moves said stop bolt to the right, so that its other end then projects from the right hand side of said controller, and said stop bolt, thus projecting, will therefore impinge against a stop wheel 44 15 and arrest the controller, when the latter, after being released, by escapement mechanism to be presently described, has rotated through an angular distance which depends upon the position of the bolt which has last 20 been so actuated, and therefore upon the particular pusher rod and the particular numeral key lever which have last been operated. When the controller so rotates, the projecting end of the last previously 25 projected stop bolt is then, by means of a cam or wedge 45 on the plate 34, and located in the path of the projecting stop bolt, returned to its normal position, in which it projects from said controller to the left instead of to 30 the right, and it is retained in that position by the annular coiled spring.

Escapement.—Secured upon the front side of said plate 2 is a guideway 46 for a stem 47 (Figs. 8 and 9) the other end of which is 35 pivotally connected to a lever 48 pivoted at 49 upon the ring 23, to the other arm of which lever is secured a spring 50, which normally tends to draw said arm to the left, and therefore said stem to the right. Said 40 stem carries a disk 51, and all of the rods 22 pass through holes in said disk.

When any numeral key has been operated, and thereby the corresponding rod moved to the left, the block 24 by which it is connected to the bell crank lever 25 then abuts 45 against said disk, and carries said disk with it to the left, thus rocking the lever 48. The long arm of said lever is connected at its extreme end by a link 52 with an arm 53 on an 50 escapement shaft 54, so that, by said movement of said lever, said escapement shaft is rocked. Said escapement shaft carries, adjustably, two disks 55, 56, spaced apart a short distance, and having respectively 55 formed in their edges notches or recesses 57, 58, offset from each other. Through said plate 34 passes a stop shaft 59, (Figs. 9, 10 and 11) which on the left side of said plate 34, carries the before-mentioned stop wheel 60 60 44, which is star-shaped, having points, any one of which is adapted to lie in the path of a bolt in the controller, which has been projected to the right, and arrest said controller if said stop shaft is then itself held fast and 65 non-rotatable. Secured upon the end of

said stop shaft upon the right hand side of the plate 34 is a large star wheel 60, having the same number of points as the wheel 44, a point of which star wheel normally abuts against the first or rear disk 55. Therefore, 70 when any numeral key has been actuated, and thereby the escapement shaft 54 rocked, the disk 55 is thereby moved until the notch 57 therein comes opposite to the point of the large star wheel 60, which can then immediately pass through said recess. This it immediately does, because, as already mentioned, the controller shaft is under constant rotational pressure, so that the previously projected bolt is pressing against a point of 75 the stop wheel 44, tending to turn it, and the shaft 59, and the star wheel 60. After said point has passed through said notch 57, it then abuts against the second disk 56, and the stop shaft is again held from further rotation. The slight movement thus given to the stop wheel 44 allows the bolt arrested thereby to move a very slight distance only. Then, upon the release of the numeral key, the escapement shaft 54 returns 80 to its original position, in which position the recess 58 in the second disk now comes opposite to the said point of the large star wheel 60, which thereupon escapes there-through, under the pressure of the stop bolt 85 on an arm of the stop wheel 44. This pressure rotates the stop shaft 59, so that the next succeeding arm of the stop wheel is brought into the path of the last projected bolt, which then impinges against said latter 90 arm, thus continuing the rotational pressure on the stop shaft rotating said shaft until the next succeeding point of the large star wheel 60 is brought up against the first escapement disk 55, and the parts are then 95 again in their normal position, ready for another operation. It will thus be seen that the extent of movement of the controller shaft is dependent upon the angular position, relatively to the stop wheel, of the 100 pusher rod actuated, and therefore upon the particular numeral key which is operated. The mechanism just described may be termed the valuating or indexing mechanism, in that it determines the extent of action of the computing mechanism to correspond with the 105 numeral keys actuated.

The members 55, 56, may be termed “escapement dogs”, and the wheel 60 may be regarded as secondary to the controller or 110 index wheel 39, which may be regarded as a primary escapement wheel. The setting devices or jacks 37 are stationary upon the machine frame, and connected to the keys to set the escapement teeth or indexing devices, 115 which are shown in the form of bolts 40, to protrude from the wheel 39 at the opposite side from the jacks 37. When protruded, these devices act as pins or teeth to drive the pinion 44, connected to the secondary escape- 120

ment wheel 60, controlled by the dog or feed device 55, 56, operated by the universal bar 51. The escapement wheel 60 is of substantially larger diameter than pinion 44, to reduce the pressure on the escapement dog device 55, 56, and minimize the resistance of the keys to the touch of the operator. The movement of the computing shaft 104 or 91 is arrested while the motor is still in movement, because the tooth of the wheel 60 strikes the arresting disk or dog 55, 56; but the return movement of the numeral key withdraws said arresting device 55, 56, to permit said shaft to be rotated by said motor. Each of the stop-bolts or indexing devices 40, after escaping from the pinion 44, is temporarily passive, that is, is out of range of any of the jacks 37. This gives said indexing devices opportunity to be restored to normal positions by the cam 45. The device 55, 56 is a key-controlled locking means for preventing the rotation of the master wheel 92 by the motor, the slip or loose connection at 66 permitting the motor to rotate while said locking means is effective.

Driving.—It has been already mentioned that the controller shaft is under constant rotational pressure, tending to rotate said shaft whenever released by the escapement mechanism. This rotational pressure is derived from any suitable motor, and for the purpose of illustration I have herein shown an electric motor 61. (Figs. 1, 22 and 23.) The shaft 62 of said motor has secured thereon a head 63, to which are pivoted three weighted governor arms 64, the ends of said arms being adapted to bear against the inner surface of a cup-shaped head 66 secured upon a shaft 67, so that said arms 40 rotate said shaft by their friction against said inner surface. Said shaft has secured thereon a bevel gear 68 which meshes with a bevel gear 69 on a shaft 70 which extends through the plate 34, and carries on its outer end a gear wheel 71 which meshes with an idle wheel 72 which in turn meshes with a gear wheel 73 upon the controller shaft. It is by this means that the controller shaft is given a constant rotational pressure, always in the same direction, rotating the same whenever released.

Computing mechanism.—The carriage 74 of the computing mechanism Figs. 1 and 12 comprises end plates 75, partitions 76, five of which partitions are extended downward, as shown at 76^x, to form end plates and partitions of a short lower and secondary portion of the computing carriage, two longitudinal bars 78, for the upper main portion of the carriage, two short longitudinal bars 78^x, for the lower secondary portion of the carriage, a casing inclosing the mechanism, cut away to form upper and lower longitudinal slots 81, 81^x, through which the two series of figures are displayed. This

computing carriage is supported from the paper carriage 83 by means of arms 84 extending from said paper carriage. It is guided, so that it will travel easily and without friction, by means of a central wheel 85, which runs in a guideway 86 secured to the frame of the typewriting machine.

The main or upper portion of the computing carriage is made just sufficiently large to contain main computing devices in a series corresponding in length with the type-writing line of the machine. But the lower portion of the carriage is much shorter, being only of a length sufficient to compute the total of the largest single column of figures ordinarily required. It is to be understood, however, that the magnitudes of the upper and lower portions of the carriage are not restricted to those shown herein, as they may be varied to suit different requirements.

Upon the left hand end of the frame of the machine is secured a bracket 87 which supports a plate 88, at a distance from the plate 34 not less than the length of the computing carriage plus the distance through which the paper carriage travels. Between said plates 88 and 34 extend two tubes 89, 90, Figs. 1 and 3 the outer ends of which are loosely mounted in sockets in said plates respectively. Within the tube 90 on the right extends a square computing or master wheel shaft 91, which, at the right hand end, passes through the plate 34, and has secured thereon means, to be presently described, for rotating said shaft 91, and, at the left hand end, is formed with a ring 92 of the same diameter as the two tubes 89, 90, and lying between the inner end of said tubes, said shaft being also formed, at the sides of said ring, with circular, hub-like portions 93, upon which the inner ends of the tubes are supported. Thus the square computing shaft rotates within the tube 90 on the right, and its hub 93 on the extreme end thereof rotates within the tube 89 on the left. The tubes and shaft are not capable of any longitudinal movement, but the tubes are confined between the plates 88 and 34. Upon said tubes, and within the carriage, travel a series of computing wheels 95, each computing wheel being formed in the middle as an internal gear wheel, having ten recesses or notches 96, and the ring 92 has, projecting therefrom, two diametrically opposite pins 97, which are adapted to enter any diametrically opposite pair of the ten notches 96, and thus serve as a master wheel to directly rotate that computing wheel only which is immediately over said ring. The tubes 89, 90, are of such length, and so arranged, that the ring 92 carrying the driving pins 97 is substantially in the same vertical plane as the writing point of the typewriter. Each computing wheel is formed

with external gear teeth 98 which mesh with gear teeth 99 formed at the side of a corresponding figure wheel 100, said figure wheels being all loosely mounted upon a 5 hollow shaft 101 which extends between the end plates of the carriage. Therefore, if the computing shaft is rotated through any given angular distance, the figure wheel, which is immediately over, or in the same 10 vertical plane as, said ring 92 on said computing shaft, is correspondingly rotated.

The secondary portion of the computing mechanism is in general similar to the main portion. It has a square computing shaft 15 91^x or master wheel (Figs. 1, 12 and 13) which extends from the plate 34 to an arm 102 at the left hand side of the main frame 1 of the machine. Instead, however, of having only one ring 92 and pins 97 thereon, fixed upon said shaft, it has a series of sleeves 92^x, each having a pair of pins 97^x thereon and a square opening therethrough so that it will fit snugly upon the square shaft 91^x and rotate therewith thus forming 20 a series of spaced master wheels. Each sleeve has also at each side a hub 93^x upon which rests the end of a tube 90^x intervening between said sleeve and the next adjacent sleeve. The tubes 90^x serve to adjustably maintain the sleeves 92^x in place. 25 By removing the retaining plate at the left of the arm 102 in Fig. 1, disconnecting the shaft 91^x from gear 103^x, and removing said shaft leftward through the arm 102, the tubes 90^x may be removed and replaced by longer or shorter tubes to vary the distance 30 between the sleeves, the longitudinal position of which sleeves can be thus varied and the number of pairs of driving pins or 35 master wheels increased or decreased accordingly, the lengths of the tubes 90^x determining the distance between the successive sleeves 92^x and thus regulating the number 40 of different columns that can be added horizontally, as hereinafter explained.

Precisely in the same manner as in the main computing mechanism, the secondary computing mechanism has a series of computing wheels 95^x, and figure wheels 100^x (Figs. 12 and 13) driven from the computing 45 wheels.

Addition and subtraction.—The computing shafts 91, 91^x, have respectively secured upon the ends projecting through the 50 plate 34 bevel gears 103, 103^x, which are adapted to be driven by a vertical shaft 104. (Figs. 1, 22, 24 and 25) having at the lower end a bevel gear 105, driven by a bevel gear 106 upon a horizontal shaft 107 having a 55 bevel gear 108 driven by a bevel gear 109 upon the controller shaft. When said controller shaft has been released by the depression of the numeral key and rotates through an angular distance corresponding 60 to the numeral key depressed, said rotation

is transmitted to the vertical shaft 104 and thence to the shafts 91, 91^x, selectively in one or the other direction by means of sliding clutches 110, 110^x, slideable upon said vertical shaft 104 but rotating therewith. By 65 means of a lever 111 the clutch 110 is adapted to be brought into operative engagement with either of two bevel gears 112^a, 112^s, loose on the shaft 104 and always in engagement with the bevel gear 103. If said lever is moved upward, then the clutch 110 70 is moved into engagement with a clutch member, formed within the upper bevel gear 112^a and causes the same to rotate with the vertical shaft 104, thereby rotating the computing shaft 91 in the direction proper for addition. If said lever is moved downward, the clutch 110 engages the clutch member of the lower bevel gear 112^s and rotates the shaft 91 oppositely to its former direction, causing the computing wheels to subtract. 75 If said lever is moved to a mediate position, the clutch 110 is out of engagement, and the computing shaft 91 does not rotate. In order to retain the lever 111 in any position to which it has been moved there is provided a loop 113, (Figs. 22 and 27) secured to the front edge of the plate 34, having three notches 114 adapted to selectively receive the edge of the lever, the 80 lever having sufficient lateral spring pressure to retain it in either notch.

112^a, 112^s, 111^a, 113^a, 114^a, indicate parts for the secondary mechanism corresponding to the parts 112^a, 112^s, 111, 113, 114, of the 85 main mechanism.

Transfer mechanism.—Upon the left side of each computing wheel 95, near the periphery, is formed a single lug or pin 115, and each time that said wheel makes a complete revolution, said pin engages one of four teeth of a primary transfer wheel 116, loose on a shaft 117, which wheel has formed, on the left hand side, gear teeth 118 which mesh with the external gear teeth 98 on the right hand side of the next computing wheel 95 to the left. Thereby said wheel on the left is partly rotated through one-tenth of a revolution. Said external gear teeth 98 of the computing wheel also mesh with teeth 115 on an auxiliary transfer wheel 119 which has also secured thereon a five-sided wheel 120, each such side being concave in an arc of a circle of slightly greater diameter than that of a transfer cylinder 123. Said transfer cylinder 123, as hereinafter described, constantly rotates and has a central metallic shaft 121 and a body portion 123, preferably of a rubber or similar resilient material. The rubber portion of the transfer cylinder 125 begins at, or opposite to, the driving pins 97 upon the computing shaft, and extends a distance to the left corresponding to the magnitude of the maximum total it is desired to compute.

When, by the advance of the lug 115, in the manner just explained, the auxiliary transfer wheel 119 has been moved through a distance corresponding to a part of one-tenth of a revolution of the computing wheel, it is then in such a position that one of its projecting portions 124, between two adjacent concave sides, has been forced into sufficiently close contact with the body of the constantly rotating transfer cylinder 123, and is rotated with the latter, until its next concave side, in turn, assumes a position over the rubber body of the transfer shaft without being in contact with it.

The transfer shaft 121 at one end passes through the plate 34 and at the other end is supported by the arm 102, and the end plates and partitions of the computing mechanism are cut away to pass said arm.

It has no longitudinal movement, but has a constant rotary movement, which is derived from the electric motor, by means of a gear wheel 125 (Fig. 23) on the shaft of the motor, meshing with an idle gear wheel 126, which in turn meshes with a gear wheel 127 (Fig. 22) on a shaft 107 carrying a bevel gear 106 which meshes with a bevel gear 105 on a vertical shaft 104' with which co-operate parts similar in their general construction and arrangement to those immediately co-operating with the vertical shaft 104, except as to the form of the clutch sleeve 110, which in this case only has a pair of teeth instead of a number thereof on each side the reason being that said shaft 104' revolves constantly at a rapid speed, and, when the direction of computation is changed, this must be done while said shaft 104 is in motion, whereas, with the computing shaft 91 the direction of motion is never changed except when the shaft 104 is at rest. By arranging the clutch mechanism for the computing shaft and for the transfer shaft to be actuated by a common lever 111, it is insured that the transfer shaft will always be rotated in unison with the computing shaft. It will be seen that all of the computing devices contained in the main computing carriage are operatively connected throughout the entire series, so that the whole series can be used for a single column or for a variable number of independent columns.

Independent denominational computation.—The above construction and arrangement of computing wheels, carrying wheels, and transfer shaft constitute what is believed to be a novel form of computing mechanism for machines, such as adding machines, in which rotary impulse is imparted directly to a series of devices in succession, corresponding to the several denominational values of the computing mechanism. In a mere registering mechanism, such as a cyclometer, in which the direct rotary move-

ment is always imparted to the terminal member of the group of computing devices, and the other devices of the group are merely for the purpose of accumulating the movements thus imparted, it is possible for all of said devices to be connected for carrying by a continuous train of gearing. But in mechanisms like the present, in which it is necessary to add directly, not only units, but also tens, hundreds, and so on, such a continuous train of gearing is inadmissible. For instance, suppose it were attempted to compute with devices so connected, and the "tens" device stood at 9, and then an addition were made to the device corresponding to the "hundreds" column, the effect would be to rotate, not only the said device, but also the device of the "tens" column. The reason for this is that, when the "tens" wheel stands at 9, its "carrying" tooth is necessarily in contact with the teeth, or similar devices, of the "hundreds" wheel or of the carrying wheel therefor, and, if the wheels are connected in a continuous train, any motion of the latter will therefore produce a corresponding motion of the former. With the present construction this difficulty is avoided in the following manner: It should first be remembered that each computing wheel is positively geared with its carrying wheel on the right, that is, the carrying wheel which connects it with the next computing wheel on the right, but its only connection with its carrying wheel on the left, which carries to the next computing wheel on the left, is through its carrying tooth. Therefore, each time that a computing wheel is rotated, its carrying wheel on the right, geared thereto, will also be rotated, but the latter wheel will not rotate the next computing wheel on the right, even though said next computing wheel, on the right be standing with its carrying tooth at the position corresponding to the display of the figure "9" in addition, or "0" in subtraction. For, when a computing wheel stands in this position, the four teeth of the carrying wheel 116 on the left can freely rotate without coming in contact with the carrying tooth 115. Consequently, there is no rotation transmitted from a computing wheel on the left to a computing wheel on the right through the carrying wheel. Since, however, the carrying tooth 115 of a computing wheel, when either "at 9," or "at 0," is in such a position that the carrying wheel does not engage the same when said carrying wheel rotates in either direction, it is evident that said computing wheel has considerable lost motion, in moving from "9" to "0" or "0" to "9," before it can be brought into operative engagement with the carrying wheel to the left, and it would therefore be impracticable to transmit, through said carrying wheel, to the computing wheel on the

left, an amount of rotation, namely, one-tenth of a revolution, equal to that transmitted to said carrying wheel from the computing wheel operated, since the first part 5 of this rotation is made without producing any motion of the said carrying wheel. To overcome this difficulty the rubber cylinder 121 may be used, for thereby, although the latter part of the motion of one-tenth of a 10 revolution of the computing wheel, after it comes in through operative engagement with the carrying wheel on the left, is effective in imparting only a partial rotation to said carrying wheel, yet this is sufficient, for it 15 is sufficient to cause a projection of the wheel 120 to engage the rubber cylinder 121, and since the latter is in constant rotation, the transfer shaft completes the work which was omitted by the computing wheel in the 20 first part of its rotation, and moves the parts through the remainder of the necessary rotation to rotate the computing wheel on the left through one-tenth of a revolution. The computing wheel hence stands in such a position, when "9" or "0", that the carrying wheel on the left can be freely rotated in either direction. The lost motion of the 25 computing wheel on the right is compensated for by providing extraneous means 30 for rotating the wheel through the latter part of its movement. The rubber cylinder 121 may also be used in other connections or for other purposes, since in any event it may assist in completing the movements of 35 the parts at the tens-carrying operation, particularly when tens are to be carried by a long row of wheels concomitantly.

Secondary mechanism.—The secondary mechanism is similar to that of the main in 40 most respects, as, for instance, in the relation of the computing wheels to the figure wheels, the general construction of the transfer shaft, and the clutch mechanism for shifting both the computing and transfer mechanism into any one of three positions to add, to subtract, or for throwing out of operation.

In order to align the figures on the figure wheels and to insure that the auxiliary 50 transfer wheel is not unduly rotated, there is provided, for each such auxiliary transfer wheel, a dog 130 (Fig. 12) having a rounded head which is pressed by a spring 131 into one of the concave sides of said auxiliary 55 wheel. It will thus be seen that each computing wheel cannot be advanced by the transfer mechanism more than one-tenth of a revolution, first, because of the dog 130, and second, because of the 60 cavity of the sides of the auxiliary transfer wheels, the points of which cannot take hold of the rubber body of the transfer shaft and rotate with it, unless positively forced thereinto.

65 The difference between the lower, or "horizontal", computing mechanism and that of the upper will be best understood by now describing the principal use for which the lower mechanism is intended. This mechanism is designed principally for 70 the purpose of obtaining cross totals of a horizontal series of independent columns of figures on the same shaft. That is, whereas the upper computing mechanism will furnish the totals for the several columns 75 thereof, the lower computing mechanism will furnish the total of all the figures in each horizontal row through said columns. For this purpose, when it is desired to use this mechanism, it is provided, first, that 80 the computing shaft of the lower mechanism rotates in unison with that of the upper mechanism, either in the same, or in the opposite direction, but always through the same angular distance, so that whenever any 85 angular movement is imparted to the upper computing shaft, and therefore to one of the upper computing wheels, a corresponding angular movement is imparted to one of the lower computing wheels. Secondly, to obtain a cross total of the figures of several 90 columns, it is necessary that the corresponding computing wheels of the horizontal or secondary computing mechanism should be engaged in succession by pairs of pins 97^x 95 on the horizontal computing shaft, simultaneously with the engagement of a single pair of pins 97 on the upper shaft with the successive computing wheels of the upper mechanism for the several columns. It is 100 understood that the spacing of the driving pins 97^x is varied to conform to the size of the horizontal computing mechanism. Means are thus actuated by the operation of 105 the numeral keys, in connection with the typewriter carriage, for vertically computing a group of independent columns of figures concomitantly, as the same are written side by side across the work-sheet; while supplementary mechanism is provided for 110 simultaneously cross-computing the successive lines which go to make up said group of vertical columns. The computing mechanisms, although having preferably a tandem arrangement, are operated in unison, 115 and may be operated in either the same or opposite directions. The individual actuating device for the upper totalizer comprises the master wheel 92 with its pins or teeth 97, and the actuating device individual to the lower or cross computer comprises the master wheels or operating pins 97^x and the shaft 91^x. Preferably, either actuator or master wheel device is operable independently of the other, by the manipulation of 120 the state-controlling levers 111, 111^x. Each of said levers may be set to neutral position, if desired, in order to silence the computing mechanism while the typewriter carriage is in the computing zone. An advan- 125

tage is gained, moreover, in providing the additional silencing key 26, because it is practicable to move either lever 111 or 111^x to silencing position while the other is in either adding or subtracting position, as may be required; and this relative adjustment of the levers need not be disturbed if it is desired to silence the computing mechanism, since it is only necessary to depress the key 26. Subsequently the key 31 may be depressed to restore the computing mechanism to activity, without the necessity for remembering to re-adjust either the lever 111 or 111^x, since they preserve the relative positions which they occupied prior to the depression of the silencing key 26.

Either of the master wheels may be set to addition, subtraction, or neutral while the other master wheel is set to either addition, subtraction, or neutral, thus making it possible to perform a great range of work on the machine. This is preferably accomplished by the provision of the shiftable means upon the shaft 104, which may turn in only a single direction, and which effects a cross connection between the two master wheel shafts 91 and 91^x, the former being a main shaft, and the latter a counter-shaft, to accord with the tandem or edge-to-edge arrangement of the master wheels.

The upper totalizer 75 may be regarded as a primary adding device, upon which separate columns may be added individually; while the totalizer 75^x may be employed, if desired, to accumulate all of the numbers included in all of the columns, thus giving a gross total of the entire sheet of figures. However, said totalizer 75^x may be used, if desired, simply to secure the cross addition of the columns line by line; the same being restored to zero at the conclusion of each line of writing, by shifting its state-controlling lever 111^x to subtraction at the same time that the number which appears in 75^x is written on the work-sheet. If this is done at the time that the last master wheel 97^x is operating on the totalizer 75^x, the latter will be returned to zero, while the corresponding sub-total will be added in the extreme right-hand portion of the upper or main totalizer 75; and at this portion of the upper totalizer 75 will be shown the gross total of the entire series of columns showing on the work-sheet. If desired, however, the upper state-controlling lever 111 may be set to neutral while the total is being written and subtracted out of the cross totalizer 75^x. This will permit the cross total to be written at any location across the work-sheet, and will also permit the entire multiple-length totalizer 75 to be employed for original addition.

If it is desired to perform subtraction in any computing zone on either one or both 65 totalizers, or to perform subtraction on one

while addition is performed on the other, it may be done by suitable manipulation of the state-controlling levers 111 and 111^x.

Grouping.—The figure wheels are visibly spaced into groups of three, each group, together with the spacing means, occupying four writing spaces of the typewriter. The spacing is preferably effected by the partitions, one of which is interposed between each group and the next, as shown in Fig. 75 1 and, occupies the fourth writing space, or a portion thereof. If only a portion, the figure wheels should be made correspondingly wider, but always so that the sum of the widths of the three figure wheels, together with that of the spacing means, is equal to four writing spaces of the typewriter. Instead of using a partition to form the spacing means, there may be used double wheel 100", as shown in Fig. 14. The partition is also preferably used to space the computing wheels into groups of three, but instead of using the partition, each third wheel of the group may be made of extra width as shown at 95". When the computing wheels are divided into groups of three by the partition, the hub 136 of the computing wheel at the left of the group rotates in a recess in the partition, said hub and the hole in the partition being of sufficient internal diameter to permit the driving pins to revolve freely therein, so as to have no effect on the computing mechanism, in case the computing shaft should be rotated at the time the operating point of the typewriter is at any fourth space of the computing mechanism. In like manner the left transfer wheel of each group is either of extra width, as shown at 116", (Fig. 18) or as shown at 116^x, extends through the partition, the four arms by which it receives its motion from the computing wheel on the right being on the right side of the partition and the gear wheel by which it transfers said motion to the computing wheel on the left being on the left side of the partition. This arrangement provides that, without disconnecting the numeral key levers from the computing mechanism, the machine is free to operate at each fourth writing space without affecting the computing wheels, so that this space can be used for pointing off the hundreds from the thousands, the thousands from the millions, and so on, and for separating the different columns thereby avoiding any derangement of the computing mechanism or error on the computation through erroneously striking a numeral key at that point. For convenience in spacing the several columns, there are provided small cover plates 140 slidable upon a suitable support adjacent to a slot, each cover plate being adapted to cover the right hand figure wheel of a group, and the adjacent spacing means, thereby distinguishing the 130

other two wheels of that group for computing cents, and spacing the same from the next group of figures; also by moving the cover plate to the beginning or to the end of 5 any column said beginning or end may be more clearly defined.

In order to ascertain at any desired time the points at which computation is taking place, either in the main or in the horizontal 10 computing mechanism, there is provided a bar 141 stationarily supported in front of the carriage and having an upwardly extending pointer 142 which is in vertical alinement with the computing pins of the 15 main computing shaft, and downwardly extending pointers 142^x which are in vertical alinement with the computing pins of the auxiliary or horizontally computing shaft. The utility of these pointers is apparent. 20 *Resetting, and error correction.*—The subtracting mechanism provides a convenient means for resetting to zero, either for a single figure wheel to correct an error, or for a series of figure wheels to begin a fresh computation. If, just before writing any total, either of vertical or of horizontal computation, the computing mechanism be reversed, then, at the time of so writing the total, the figure wheels giving such total will be there- 25 30 by reset to zero.

I claim:—

1. In a computing attachment for a typewriter, the combination of numeral keys, case-shifting mechanism including a shift 35 key, computing mechanism, links for operatively connecting said numeral keys with said computing mechanism, a slide bar for simultaneously moving said links to connect or disconnect said computing mechanism, 40 and means actuated with the shift key for so shifting the slide bar, substantially as described.

2. In a computing attachment for a typewriter, the combination of numeral keys, 45 case-shifting mechanism including key levers, a shift key, computing mechanism, links for connecting said levers with the computing mechanism, means carried by said key levers adapted to be engaged by 50 said links, a slide for simultaneously shifting all of said links to so engage said means, and means actuated by the depression of the shift key, for shifting said slide bar to dis- 55 engage said links, substantially as described.

3. In a computing attachment for a typewriter, the combination of numeral keys, case-shifting mechanism including key levers, a shift key, computing mechanism, links for connecting said levers with the 60 computing mechanism, means carried by said key levers adapted to be engaged by said links, a slide for simultaneously shifting all of said links to so engage said means, means actuated by the depression of the 65 shift key for shifting said slide bar to dis-

engage said links, and a device for shifting said slide bar independently of the shift key, substantially as described.

4. In a computing attachment for a typewriter, the combination of numeral keys, 70 case-shifting mechanism including a shift key, computing mechanism, connections between said numeral keys and computing mechanism, means whereby the operation of the shift key disconnects said connections, 75 an independent key for disconnecting said connections from the numeral keys, and a second independent key for again normally connecting them, substantially as described.

5. In a computing attachment for typewriters, the combination of a numeral key, a rotary controller, bolts therein, a corresponding series of bell crank levers, rods connected with the bell crank levers and operatively connected with said numeral keys, 85 each bell crank lever when actuated being adapted to project a bolt through the controller, an escapement device for arresting the said controller, and means for actuating said escapement device, comprising a slideable rod, a disk carried thereby having openings through which the first named rods pass, said disk being adapted to be moved by any one of the bell crank levers when operated, and a lever operatively connected 90 with said rod and with the escapement to withdraw the same, substantially as described.

6. In an apparatus of the character described, the combination of a step-by-step 100 feeding carriage having upper and lower computing mechanisms, individual parallel actuating shafts for said mechanisms, each shaft carrying a master wheel, and means independent of either of said mechanisms, 105 whereby said shafts may be rotated in unison, substantially as described.

7. In an apparatus of the character described, the combination of a step-by-step feeding carriage having upper and lower 110 computing mechanisms having fixed positions therein, individual parallel actuating shafts for said mechanisms, each shaft carrying a master wheel, and means, independent of either of said mechanisms, whereby 115 said shafts may be rotated in unison, substantially as described.

8. In an apparatus of the character described, the combination of a typewriter carriage, a frame having upper and lower computing mechanisms having fixed positions therein, moving in a step by step movement with the typewriter carriage at the same direction through the entire travel of the latter, individual parallel actuating shafts 125 for said mechanisms, and means, independent of either of said mechanisms, whereby said shafts may be rotated in unison, substantially as described.

9. In an apparatus of the character de- 130

scribed, the combination of a step-by-step feeding carriage having two series of computing mechanisms having a tandem arrangement, an actuating shaft for each mechanism, whereby each actuating shaft exclusively actuates its corresponding mechanism, and means whereby said actuating shafts may be rotated in unison, substantially as described.

10. 10. In an apparatus of the character described, the combination of upper and lower computing mechanisms each having a series of computing devices, a frame in which said mechanisms are fixedly secured, individual shafts with actuators thereon for the respective mechanisms, and means for causing said actuators to engage in succession simultaneously the computing devices of the two mechanisms, substantially as described.

20. 11. In an apparatus of the character described, the combination of a frame, a plurality of computing mechanisms, fixed relatively to the frame and each having a series of computing devices, individual actuator shafts and actuators thereon, means for operatively connecting said shafts, each actuator shaft exclusively rotating the computing devices of the corresponding mechanism, and means whereby the actuators of 30 the respective shafts can be caused to simultaneously engage the computing devices of the two mechanisms.

12. In an apparatus of the character described, the combination of a step-by-step feeding carriage having upper and lower computing mechanisms, individual parallel actuating shafts for said mechanisms, each shaft carrying a master wheel, and means, independent of either of said mechanisms, 40 for rotating said shafts in unison either in the same or in opposite directions.

13. In an apparatus of the character described, the combination of a step-by-step feeding carriage having upper and lower computing mechanisms having fixed positions thereon, individual parallel actuating shafts for said mechanisms, each shaft carrying a master wheel, and means, independent of either of said mechanisms, 45 for rotating said shafts in unison either in the same or in opposite directions.

14. In an apparatus of the character described, the combination of a typewriter carriage, a frame having upper and lower computing mechanisms having fixed positions therein, moving in a step by step movement with the typewriter carriage in the same direction through the entire travel of the latter, individual parallel actuating shafts for said mechanisms, and means, independent of either of said mechanisms, 55 for rotating said shafts in unison either in the same or in opposite directions.

15. In an apparatus of the character de-

scribed, the combination of a step-by-step feeding carriage having two series of computing mechanisms, an actuating shaft for each mechanism, each shaft carrying a master wheel, means for enabling each actuating shaft to exclusively actuate its corresponding mechanism and means for rotating said shafts in unison either in the same or in opposite directions.

16. In an apparatus of the character described, the combination of a carriage having upper and lower computing mechanisms, individual parallel actuating shafts for said mechanisms, and means, independent of either of said mechanisms, for rotating either of said shafts independently of the other in either direction.

17. In an apparatus of the character described, the combination of a step-by-step feeding carriage, computing mechanisms, individual parallel actuating shafts for said mechanisms, each shaft carrying a master wheel, and means for rotating either of said shafts either independently of or simultaneously with the other in either direction.

18. In an apparatus of the character described, the combination of a typewriter carriage, a frame having upper and lower computing mechanisms having fixed positions therein, moving in a step by step movement with the typewriter carriage in the same direction through the entire travel of the latter, individual parallel actuating shafts for said mechanisms, and means, independent of either of said mechanisms, for rotating either of said shafts in either direction while the other shaft is stationary.

19. In an apparatus of the character described, the combination of a step-by-step feeding carriage having two series of computing mechanisms, an actuating shaft for each mechanism, each shaft carrying a master wheel, means whereby each actuating shaft exclusively actuates its corresponding mechanism, and means actuated independently of either mechanism for rotating either of said shafts independently of the other in either direction, substantially as described.

20. In an apparatus of the character described, the combination of a step-by-step feeding carriage having two series of computing devices, an operating shaft for each series, each shaft carrying a master wheel, and means for rotating said shafts in unison, either in the same or in opposite directions.

21. In an apparatus of the character described, the combination of two series of computing devices, a separate and independently operable computing shaft for each series, each shaft being operable while the other is motionless, and means for rotating said shafts in unison.

22. In an apparatus of the character described, the combination of two series of computing devices, a separate computing shaft for each series, means for producing 5 a relative longitudinal movement of each shaft and its corresponding series of computing devices, one of said shafts having a single operating means adapted to engage in succession the computing devices, and the 10 other of said shafts having a longitudinal series of such operating means, and means for rotating said shafts in unison.
23. In an apparatus of the character described, the combination with a typewriter 15 having a paper carriage, of a computing carriage, and means whereby said computing carriage moves with the paper carriage in the same direction and with the same speed, said computing carriage having two 20 series of computing devices, a separate and independently operable operating shaft for each series, and means for rotating said shafts in unison.
24. In an apparatus of the character described, the combination with a typewriter 25 having a paper carriage, of a computing carriage, and means whereby said computing carriage moves with the paper carriage in the same direction and with the same speed, said computing carriage having two 30 series of computing devices, separate and independently operable operating means for the two series, and means to cause said operating means to operate simultaneously and 35 in unison upon the computing devices of the two series to rotate them at all times through the same angular distance.
25. In an apparatus of the character described, the combination with a typewriter 40 having a paper carriage, of a computing carriage, means for causing said computing carriage to move with said paper carriage in the same direction and at the same speed, said computing carriage having two 45 series of computing devices, separate and independently operable shafts for said series, means for rotating said shafts in unison, one of said shafts having thereon 50 a plurality of means for operatively connecting said shaft with the computing devices of its series, whereby each computing device may be actuated a plurality of times in succession in a complete movement of the computing and paper carriages.
55. 26. In an apparatus of the character described, the combination of a computing mechanism consisting of a series of computing devices, a shaft for operating said devices, means for producing a relative 60 movement of the shaft and computing devices, a plurality of parts carried by the shaft and longitudinally spaced from each other at equal distances on said shaft and arranged to act in succession upon said computing devices in said relative movement, and means for changing the direction of rotation of said shaft at any point desired in said relative movement.
27. In an apparatus of the character described, the combination of numeral keys, 70 a carriage, a series of computing devices, a shaft for operating said computing devices, means for effecting relative movement between said computing devices and said shaft, a plurality of parts spaced on 75 the shaft and adapted to engage said computing devices in succession, means actuated through the operation of a numeral key for rotating said shaft, and means for reversing the direction of said shaft at any 80 point in the movement of the computing device.
28. In an apparatus of the character described, the combination of a carriage having two series of computing mechanisms, 85 an actuating shaft for each mechanism, means to enable each actuating shaft exclusively to actuate its corresponding mechanism and means to cause said shafts to rotate in unison either in the same or in 90 opposite directions.
29. In an apparatus of the character described, the combination of a carriage having upper and lower series of computing devices, parallel shafts for individually actuating said series, one of said shafts having thereon a plurality of longitudinally spaced devices for operating in succession the computing devices of its series, and 95 means to cause said operating shafts to rotate in unison.
30. In an apparatus of the character described, the combination of a step-by-step feeding carriage having computing mechanisms, individual parallel actuating shafts 100 for said mechanisms, each shaft carrying a master wheel, and means, independent of either of said mechanisms, for rotating either of said shafts independently of the other.
31. In an apparatus of the character described, the combination of a step-by-step feeding carriage having upper and lower computing mechanisms having fixed positions thereon, individual parallel actuating shafts for said mechanisms, each shaft carrying a master wheel, and means, independent of either of said mechanisms, for rotating either of said shafts independently of the other in either direction.
32. In an apparatus of the character described, the combination of a step-by-step feeding carriage having two series of computing devices, an operating shaft for each series, one of said shafts carrying a master wheel and another of said shafts having thereon a plurality of longitudinally-spaced master wheels for operating upon said com-

puting devices in succession, and means for rotating either shaft independently of the other in either direction.

33. In an apparatus of the character described, the combination of two series of computing mechanisms, individual shafts for said computing mechanisms, means for producing a relative movement of said shafts and computing mechanisms, the second shaft having thereon a plurality of longitudinally spaced actuators for operating in succession upon the computing devices of its mechanism, and the first shaft having a single such actuator, the first series of computing mechanisms being divided into as many totalizers as there are actuators on said second shaft, and means for rotating said shafts in unison.

34. In an apparatus of the character described, the combination of two series of computing mechanisms, individual shafts for said computing mechanisms, means for producing a relative movement of said shafts and computing mechanisms, the second shaft having thereon a plurality of longitudinally spaced actuators for operating in succession upon the computing devices of its mechanism, and the first shaft having a single such actuator, the first series of computing mechanisms being divided into as many totalizers as there are actuators on said second shaft, and means for rotating said shafts in unison.

35. In an apparatus of the character described, the combination of two series of computing mechanisms, individual shafts for said computing mechanisms, means for producing a relative movement of said shafts and computing mechanism, the second shaft having thereon a plurality of longitudinally spaced actuators for operating in succession upon the computing devices of its mechanism, and the first shaft having a single such actuator, the first series of computing mechanisms being divided into as many totalizers as there are actuators on said second shaft, and means for rotating said shafts in unison.

36. In an apparatus of the character described, the combination of a step-by-step feeding carriage having two series of computing devices, an operating shaft for each series, one of said shafts carrying a master wheel and another of said shafts having thereon a plurality of longitudinally-spaced master wheels for operating upon said computing devices in succession, and means for rotating said shafts in unison, either in the same or in the opposite direction.

37. In an apparatus of the character described, the combination of a step-by-step feeding carriage having two series of computing devices, an operating shaft for each series, one of said shafts carrying a master wheel and another of said shafts having

thereon a plurality of longitudinally-spaced master wheels for operating upon said computing devices in succession, and means for rotating said shafts in unison, either of said shafts being operable independently of the other.

38. In an apparatus of the character described, the combination of a step-by-step feeding carriage having two series of computing devices, an operating shaft for each series, one of said shafts carrying a master wheel and another of said shafts having thereon a plurality of longitudinally-spaced master wheels for operating upon said computing devices in succession, and means for rotating said shafts in unison, either of said shafts being disconnectible from the rotating means independently of the other.

39. In an apparatus of the character described, the combination of a series of computing wheels, a hollow shaft passing therethrough, and a torque-transmitting shaft within the hollow shaft, having a sleeve thereon with a cross-section corresponding to the cross-section of the hollow shaft, said sleeve having a rounded hub upon which the end of the hollow shaft rests, and said sleeve having a part extending radially beyond said hollow shaft and adapted to engage said computing wheels to rotate the same.

40. In an apparatus of the character described, the combination of a series of computing wheels, a torque-transmitting shaft passing through said computing wheels, a series of sleeves thereon having an internal cross-section corresponding to the cross-section of the shaft, each sleeve being provided with means for engaging a computing wheel to rotate the same and having on each side of said means a hub, tubes between the sleeves, their ends supported on said hubs, and means for rotating said shaft.

41. In an apparatus of the character described, the combination of a series of computing devices, means for imparting rotary motion thereto, and means for "carrying" from one device to the next, comprising a transfer shaft, and means for imparting to said shaft a constant rotation.

42. In an apparatus of the character described, the combination of a series of computing wheels, a computing shaft, a transfer shaft for "carrying" from one computing wheel to the next, a motor, a connection between said motor and transfer shaft, for rotating the latter shaft uninterruptedly from the movement of the motor, and a connection between the motor and the computing shaft, for permitting the latter to rotate only upon the depression of a numeral key.

43. In an apparatus of the character described, the combination of a series of computing wheels, a series of gear wheels, geared to said computing wheels, each gear wheel having secured thereto a star-shaped wheel.

with concave sides and a shaft freely rotated in the concavity of any of said sides and adapted to engage an intermediate portion of said wheel when the latter has been turned, and means for rotating the latter shaft, substantially as described.

44. In an apparatus of the character described, the combination of computing wheels, a series of gear wheels, geared to said computing wheels, each gear wheel having secured thereto a star-shaped wheel with concave sides and a shaft freely rotated in the concavity of any of said sides and adapted to engage an intermediate portion of said wheel when the latter has been turned, and means for constantly rotating the latter shaft, substantially as described.

45. In an apparatus of the character described, the combination of a series of computing wheels, a series of gear wheels, geared to said computing wheels, each gear wheel having secured thereto a star-shaped wheel with concave sides and a shaft having a yielding body portion and freely rotated in the concavity of any of said sides and adapted to engage an intermediate portion of said wheel when the latter has been turned, and means for rotating the latter shaft, substantially as described.

46. In an apparatus of the character described, the combination of a series of computing wheels, a computing shaft, a transfer shaft for "carrying" from one computing wheel to the next, a motor, a connection between said motor and transfer shaft, for rotating the latter shaft uninterruptedly from the movement of the motor, a connection between the motor and the computing shaft, for permitting the latter to rotate only upon the depression of a numeral key, and means for reversing the direction of rotation of both shafts.

47. In an apparatus of the character described, the combination of a series of computing wheels, transfer wheels for "carrying" from one computing wheel to the next, auxiliary transfer wheels meshing with the computing wheels, and a transfer shaft adapted to engage the auxiliary transfer wheels to sufficiently complete the rotation of the same when partly turned by the computing wheels, said auxiliary wheels having concave sides, and the transfer shaft being adapted to rotate freely in the concavity of a side but to engage the intermediate portion when the corresponding wheel is partly advanced, substantially as described.

48. In an apparatus of the character described, the combination of a series of computing wheels, a series of gear wheels, geared to said computing wheels, each gear wheel having secured thereto a star-shaped wheel with concave sides and a shaft freely rotated in the concavity of any of said sides and adapted to engage an intermediate portion

of said wheel when the latter has been turned, a spring-actuated locking device adapted to engage another of said concavities, and means for rotating the latter shaft, substantially as described.

49. The combination of typewriting and computing mechanism, means for connecting said computing mechanism with the numeral keys of the typewriter whereby said computing mechanism will be operated by the operating of the numeral keys, means for disconnecting the same, whereby said numeral keys may be operated without operating said computing mechanism, means actuated by the depression of a key for connecting said computing mechanism with the numeral keys of the typewriter so that said mechanism will be operated by the depression of a numeral key, a third key and means for automatically disconnecting said computing mechanism from said numeral keys, by the operation of said third key.

50. The combination with a plurality of computing devices having a tandem arrangement, of a plurality of actuating means for entering a series of distinct numbers separately and independently of one another in one of said devices in effecting a series of separate and independent vertical computations, and concomitantly running up a single inter-computation of the same numbers in another of said devices to effect cross computation, and a train of driving mechanism extending from one of said actuating means to the other.

51. The combination with a plurality of computing devices rigidly connected, of actuating means for entering a series of distinct numbers separately and independently of one another in one of said devices in effecting a series of separate and independent vertical computations, and concomitantly running up a single inter-computation of the same numbers in another of said devices to effect cross computation, and shiftable computation-controlling means enabling said devices to act in unison as to the character of calculation.

52. The combination with a plurality of computing devices rigidly connected, of actuating means for entering a series of distinct numbers separately and independently of one another in one of said devices in effecting a series of separate and independent vertical computations, and concomitantly running up a single inter-computation of the same numbers in another of said devices to effect cross computation, and computation-controlling means enabling said devices to act in unison as to the character of calculation and also enabling different types of calculation to be carried on at different points in one of said devices during one and the same movement thereof.

53. The combination with a plurality of

computing devices, of actuating means for entering a series of distinct numbers separately and independently of one another in one of said devices in effecting a series of 5 separate and independent computations, and concomitantly running up a single inter-computation of the same numbers in another of said devices to effect cross computation, and shiftable computation-controlling means 10 enabling said devices in simultaneous operation to act either oppositely or in agreement as to the character of calculation.

54. The combination with a plurality of computing devices, of a carriage, actuating 15 means to coöperate with said carriage for entering a series of distinct numbers separately and independently of one another in one of said devices in effecting a series of 20 separate and independent vertical computations, and concomitantly running up a single inter-computation of the same numbers in another of said devices to effect cross computation, and computation-controlling means 25 enabling said devices to act in agreement or disagreement as to the character of calculation, said computation-controlling means shiftable at different points in the 30 progress of said carriage, to enable different types of calculation to be carried on at different points in one of said devices during one and the same movement of said carriage.

55. The combination of a plurality of superposed computing heads or totalizing devices rigidly connected to travel together 35 at all times; one being arranged to accumulate amounts of a series of individual columns, and the other being arranged to accumulate the entire total of all of said 40 columns.

56. The combination of a plurality of superposed computing heads or totalizing devices rigidly connected to travel together at all times; one being arranged to accumulate amounts of a series of individual columns, and the other being arranged to accumulate the entire total of all of said columns, and indexing means for indicating the active element of each device at all 50 points of the movement thereof.

57. The combination with a typewriting mechanism including numeral keys arranged to cause the writing of numerals and characters other than numerals, shifting means for determining the characters written at 55 the actuation of said numeral keys, computing mechanism, connections between said computing mechanism and said keys, means controlled by said shifting means for disconnecting said computing mechanism from 60 said numeral keys, other means for disconnecting said computing mechanism from said numeral keys to render said computing mechanism inactive, and means operated at the actuation of said last-mentioned means

for disconnecting said shifting means from 65 said computing mechanism.

58. The combination with a typewriting mechanism including numeral keys arranged to cause the writing of numerals and characters other than numerals, shifting means 70 for determining the characters written at the actuation of said numeral keys, computing mechanism, connections between said computing mechanism and said keys, means controlled by said shifting means for disconnecting 75 said computing mechanism from said numeral keys, other means for disconnecting said computing mechanism from said numeral keys to render said computing mechanism inactive, means operated at 80 the actuation of said last-mentioned means for disconnecting said shifting means from said computing mechanism, and means for delaying the disconnection of said computing mechanism from said numeral keys until 85 said computing mechanism has been disconnected from said shifting means.

59. The combination with a typewriting mechanism including numeral keys, of a computing mechanism actuatable from said 90 numeral keys, a shift key for determining the characters written by said numeral keys, means for disconnecting said computing mechanism from said numeral keys at the actuation of said shift key, a key for controlling the connection of said computing mechanism to said numeral keys to determine the active periods of said computing mechanism, and connections operated by 95 said last-mentioned key for disconnecting 100 said means from said shift key, so as to free the control of said computing mechanism from said shift key when said computing mechanism is disconnected from said 105 numeral key by said last-mentioned key.

60. The combination with a typewriting mechanism including numeral keys, of a computing mechanism actuatable from said numeral keys, a shift key for determining the characters written by said numeral keys, means for disconnecting said computing mechanism from said numeral keys at the actuation of said shift key, a key for controlling the connection of said computing mechanism to said numeral keys to determine 110 the active periods of said computing mechanism, connections operated by said last-mentioned key for disconnecting said means from said shift key, so as to free the control of said computing mechanism from 115 said shift key when said computing mechanism is disconnected from said numeral key by said last-mentioned key, and yielding means for delaying the disconnection of said computing mechanism from said 120 numeral keys until after said means has been disconnected from said shift key.

61. The combination with a typewriting

- mechanism including numeral keys, of a computing mechanism connected to be actuated by said numeral keys, "in" and "out" keys for determining the active and 5 inactive periods of said computing mechanism, a shift key for determining the characters written by said numeral keys, means controlled by said shift key for determining the connection between said computing 10 mechanism and said numeral keys, said means being in turn controlled by said "in" and "out" keys to determine the control of said computing mechanism by said shift key.
- 15 62. In a computing machine, the combination with a key-controlled drive shaft, of a series of superposed computing heads, each having a master wheel shaft connected to said drive shaft.
- 20 63. In a computing machine, the combination with a key-controlled drive shaft, of a series of superposed computing heads, each having a master wheel shaft connected to said drive shaft, and means to enable 25 said drive shaft to turn certain of said master wheel shafts in either direction.
- 25 64. The combination with a typewriting mechanism including a set of numeral keys and having a shifting means for determining 30 the case of the characters written thereby, of a computing mechanism, connections extending from said keys to said computing mechanism, a shiftable manual device for disconnecting said connections from said 35 keys, and means for rendering said connections controllable by said shifting means when said connections are operatively connected to the keys, and free from control by 40 said shifting means when said connections are not operatively connected to the keys, whereby the shifting means may be freely operated without liability of reconnecting said connections to said keys.
- 35 65. The combination with a plurality of 45 parallelly-arranged superposed computing heads, of a master wheel shaft for each of said heads, and a drive shaft common to all of said master wheel shafts and thus to all of said computing heads.
- 50 66. The combination with a plurality of superposed computing heads, of an individual master wheel shaft for each of said heads, and a drive shaft common to all of said master wheel shafts.
- 55 67. The combination with a plurality of superposed computing heads, of a plurality of numeral keys for controlling the running up of numbers into said computing heads, a 60 master wheel shaft individual to each of said computing heads, a master wheel on each of said master wheel shafts for the corresponding computing head, a drive shaft common to all of said master wheel shafts, and means for enabling said keys to control the extent of movement of said drive shaft 65 and thus of said master wheel shafts.
- 65 68. The combination with a plurality of computing heads offset out of horizontal alignment with each other, of a plurality of numeral keys for controlling the running up 70 of numbers into said computing heads, a master wheel shaft individual to each of said computing heads, a master wheel on each of said master wheel shafts for the corresponding computing head, a drive shaft 75 common to all of said master wheel shafts, means for enabling said keys to control the extent of movement of said drive shaft and thus of said master wheel shafts, and individual means for each of said master wheel 80 shafts for controlling the character and direction of drive of all of said master wheel shafts by said drive shaft.
- 70 69. The combination with two series of computing devices, of a separate and independently operable computing shaft for each 85 series, means whereby said shafts can rotate in unison, and means for selectively determining whether said shafts shall rotate in the same or opposite directions. 90
- 75 70. The combination with a shift key mechanism, of an "out" key mechanism, and a yielding spring connection extending from one of said mechanisms to the other 95 to render their actions interdependent.
- 80 71. The combination with a series of computing wheels, of a series of numeral keys, means for driving said computing wheels one by one as the numeral keys are actuated, a continuously acting carry-over mechanism 100 for said computing wheels acting for the running in of each digit to enable the carrying of tens between higher and lower denominations of said computing wheels, and a continuously-acting source of power for 105 driving said carry-over mechanism.
- 85 72. The combination with a series of computing wheels, of a source of power, a carry-over mechanism for said computing wheels, a train of gearing from said source of power 110 to said computing wheels to operate the latter one after another as the keys are successively struck, a series of numeral keys for controlling the actuation of said computing wheels by said source of power through said 115 train of gearing amounts corresponding to the particular numeral keys actuated, and a second train of gearing between said source of power and said carry-over mechanism, said trains of gearing being independent of 120 each other as to the extent which they are rotated by said source of power.
- 90 73. The combination with a series of computing wheels, of a carry-over mechanism for said computing wheels, a source of 125 power, a train of gearing between said source of power and said computing wheels to operate the latter one after another as the

keys are successively struck, a series of numeral keys for determining the extent of rotation of said computing wheels by said source of power through the intermediary 5 of said train of gearing, and a second train of gearing between said source of power and said carry-over mechanism, said source of power rotating said first-mentioned train of gearing amounts dependent upon the 10 particular numeral keys actuated, and said source of power rotating said carry-over mechanism amounts largely in excess of the amounts which said first-mentioned train of gearing is rotated by said source of power, 15 and sufficient to carry over throughout the entire series from lowest to highest denomination at the operation of any one of said numeral keys.

74. The combination with a series of computing wheels, of a carry-over mechanism 20 for said computing wheels, a source of power, to operate the latter one after another as the keys are successively struck, a series of numeral keys for controlling the 25 rotation of said computing wheels by said source of power, and driving connections between said source of power and both said computing wheels and said carry-over mechanism to enable the rotation of said 30 computing wheels amounts determined by the numeral keys, and further to enable the continuation of the actuation of said carry-over mechanism by said source of power after the rotation of said computing wheels by said source of power has 35 ceased.

75. The combination with a series of computing wheels, of a carry-over mechanism for said computing wheels, a source of 40 power, a drive from said source of power to said computing wheels, to operate the latter one after another as the keys are successively struck, a series of numeral keys for controlling the drive of said computing 45 wheels by said source of power, said drive driving said computing wheels just enough to run up numbers corresponding to the numeral keys actuated, and a drive from said source of power to said carry-over mechanism to rotate said carry-over 50 mechanism amounts irrespective of the amounts said computing wheels are rotated by said source of power.

76. The combination with a main totalizer 55 and a relatively short totalizer connected thereto, of a single master wheel for said main totalizer and a series of master wheels for repeatedly operating said short totalizer during a single traverse of the main totalizer by its own master wheel, and means for effecting a concomitant relative movement between the totalizers and the master wheels.

77. The combination with a plurality of 60 totalizers, of a master wheel shaft for each

of said totalizers, a drive shaft common to all of said master wheel shafts for driving the same like amounts, a carry-over mechanism for each of said totalizers, an assisting shaft for each of said carry-over mechanisms, and a drive shaft common to all of 70 said assisting shafts.

78. The combination with a plurality of totalizers, of a master wheel shaft for each 75 of said totalizers, a drive shaft common to all of said master wheel shafts for driving the same like amounts, a carry-over mechanism for each of said totalizers, an assisting shaft for each of said carry-over mechanisms, a drive shaft common to all of 80 said assisting shafts, a series of numeral keys, and a source of power common to both of said drive shafts.

79. The combination with a plurality of totalizers, of a master wheel shaft for each 85 of said totalizers, a drive shaft common to all of said master wheel shafts for driving the same like amounts, a carry-over mechanism for each of said totalizers, an assisting shaft for each of said carry-over mechanisms, a drive shaft common to all of 90 said assisting shafts, a series of numeral keys, a source of power common to both of said drive shafts, and connections between said source of power and said drive shafts, the 95 connections between said source of power and said first-mentioned drive shaft being dependent for their extent of actuation on the particular numeral keys struck and the connections between said source of power 100 and said second-mentioned drive shaft being independent in extent of its movement with respect to the particular numeral keys struck.

80. The combination with a computing 105 mechanism, of a series of numeral keys for controlling the action of said computing mechanism, connections between said numeral keys and said computing mechanism, said connections being adjustable between 110 effective and ineffective positions, a typewriting mechanism actuated by said numeral keys, said typewriting mechanism having a platen shiftable between upper and lower case positions to determine the 115 writing of upper and lower case characters, and a shift key for controlling the position of said platen, an "in" key for rendering said connections effective, an "out" key for rendering said connections ineffective, and 120 connections between said "in" and "out" keys and said shift key for rendering the actions of the same interdependent.

81. In a computing machine, the combination with numeral keys and computing 125 wheels, of carry-over devices for said wheels, an escapement for determining how far said wheels shall be driven, a shaft rotated continuously to drive said carry-over devices, and a motor for driving said wheels and said 130

carry-over devices through said escapement and said shaft.

82. The combination with a series of computing wheels, of actuating mechanism for driving said computing wheels, carry-over mechanism for said computing wheels, acting concomitantly with said actuating mechanism, motive means for driving both said carry-over mechanism and said actuating mechanism, a train of connections between said motive means and said actuating mechanism having a point of interruption permitting a continued action of said motive means after said actuating mechanism has completed its drive, and a continuous train of gearing between said motive means and said carry-over mechanism enabling the drive of said carry-over mechanism by said motive means while said actuating mechanism is silent.

83. The combination with a series of computing wheels, of actuating mechanism for said computing wheels, tens-carrying mechanism for said computing wheels, motive means for driving both said tens-carrying mechanism and said actuating mechanism, a train of gearing between said motive means and said actuating mechanism having a point of interruption therein enabling a continued movement of said motive means after said actuating mechanism has completed an operation, and a train of gearing connecting said motive means to said tens-carrying mechanism to enable the drive of said tens-carrying mechanism by said motive means, said last-mentioned train of gearing connecting to said motive means between the point of interruption of said first-mentioned train of gearing and said motive means, so that said tens-carrying mechanism may be driven after said actuating mechanism has become silent.

84. The combination with computing wheels, of actuating mechanism for said computing wheels, tens-carrying mechanism for said computing wheels, motive means for driving both said actuating mechanism and said tens-carrying mechanism, a train of gearing between said motive means and said actuating mechanism including a valuating mechanism for determining the extent of movement of said actuating mechanism, said valuating mechanism being connected to said motive means so as to permit a continued movement of said motive means after said valuating mechanism has terminated the movement of said actuating mechanism, and a drive train from said motive means to said tens-carrying mechanism independent of said valuating mechanism, so as to permit a movement of said tens-carrying mechanism independent of the extent of action of said valuating mechanism.

85. The combination with computing wheels, of actuating mechanism for said

computing wheels, carry-over mechanism for said computing wheels, driving means for both said actuating mechanism and said carry-over mechanism, and driving connections from said driving means to said actuating mechanism, and to said carry-over mechanism enabling carry-over actions by said carry-over mechanism to be initiated during the running up of a number on one of said computing wheels by said actuating mechanism and to continue without interruption after the completion of the movement of such computing wheel.

86. The combination with a major computing device divisible into sections, each having a capacity of a computing zone, of a minor computing device having a capacity corresponding to a single section of said major computing device, actuating mechanism for each of said computing devices, a series of numeral keys, driving means controlled by said numeral keys and common to both said computing devices, so that the same numbers may be simultaneously run up in both of said computing devices, and traversing mechanism for effecting a continuous relative movement for a transverse line of numbers between both major and minor computing devices and their actuating mechanisms, whereby the numbers of a series of computing zones may be accumulated zone by zone in the individual sections of said major computing device and number upon number for all zones in the single section of said minor computing device.

87. The combination with a major computing device divisible into sections, each having a capacity of a computing zone, of a minor computing device having a capacity corresponding to a single section of said major computing device, actuating mechanism for each of said computing devices, a series of numeral keys, driving means controlled by said numeral keys and common to both said computing devices, so that the same numbers may be simultaneously run up in both of said computing devices, traversing mechanism for effecting a continuous relative movement for a transverse line of numbers between both said major and minor computing devices and their actuating mechanisms, whereby the numbers of a series of computing zones may be accumulated zone by zone in the individual sections of said major computing device and number upon number for all zones in the single section of said minor computing device, and state-controlling mechanisms for both said major and minor computing devices separably operable and at will at any point in the continuous relative movement between said computing devices and their actuating mechanisms, so as to enable different types of computing actions selectively at any point.

in a line of relative movement, and also so as to enable the same or different types of computation to be simultaneously carried on by said major and minor computing devices.

88. The combination with a plurality of computing devices arranged in tandem, of actuating mechanisms individual to each device and independently driven, and having a corresponding tandem arrangement, and a traversing mechanism for effecting a concomitant relative traveling movement between said computing devices and their actuating mechanisms.

89. The combination with a plurality of computing devices having a tandem arrangement, of an actuating mechanism for each of said computing devices, each including a horizontal shaft, a common shaft for driving all of said horizontal shafts, a valuating mechanism for determining the extent of drive of said drive shaft, and a series of numeral keys for determining the action of said valuating mechanism.

90. The combination with a plurality of computing devices having a tandem arrangement, of an actuating mechanism for each of said computing devices, each including a horizontal shaft, a common countershaft for driving all of said horizontal shafts, a valuating mechanism for determining the extent of drive of said countershaft, a series of numeral keys for determining the action of said valuating mechanism, and individual change-drive connections between each of said horizontal shafts and said countershaft, so as to vary the state individually of each of said actuating mechanisms.

91. The combination with typewriting mechanism, of computing mechanism, a set of numeral keys for controlling both said typewriting mechanism and said computing mechanism, a set of connections between said numeral keys and said computing mechanism, said connections disconnectible from said numeral keys, a shift key connected to control the writing of upper and lower case characters, and also connected to disconnect said set of connections from said numeral keys when writing upper case characters, and means for simultaneously disconnecting said numeral keys and said shift key from said connections.

92. In a combined typewriting and computing machine, the combination with numeral keys and computing wheels, of two manually operable devices, one for connecting said keys to said wheels and the other for disconnecting said keys from said wheels, a case-shift mechanism, and a master device connected to said case-shift mechanism for disconnecting the keys from the wheels at the operation of the case-shift key.

93. In a combined typewriting and computing machine, the combination with a set

of numeral keys and computing wheels, of a set of mechanical connections extending from said numeral keys to control said computing wheels, a manually operable device, a case-shift key, and mechanism extending from said connections to both said manually operable and said case-shift key, to enable either of them to disconnect said numeral keys from said series of mechanical connections.

94. The combination with a typewriting mechanism having a case-shift device, of a computing mechanism, a set of numeral keys for controlling the actions of both said computing mechanism and said typewriting mechanism, a set of connections being provided between said numeral keys and said computing mechanism, to enable the control of said computing mechanism by said numeral keys, and means controlled by said case-shift device for interrupting the joinder of all of said connections with said numeral keys, so as to enable said computing mechanism to be free and clear of said numeral keys while writing different case characters.

95. In an apparatus of the character described, the combination with a typewriting mechanism including a carriage, of a series of computing wheels, a computing shaft therefor, a transfer shaft, transfer mechanism carried by said shaft and adapted to transfer from one computing wheel to the next, an operative connection between said computing and transfer shafts whereby either is rotated with the rotation of the other, and means for rotating one of said shafts.

96. In an apparatus of the character described, the combination of computing wheels, a computing shaft, means for operatively connecting said wheels in succession with said shaft, a motor for rotating said shaft, an operative connection between said motor and shaft including friction devices, means for arresting the movement of said shaft while said motor is still in movement, a series of numeral keys, and means actuated by the movement of a numeral key for withdrawing said arresting means to permit the shaft to be rotated by the motor.

97. In an apparatus of the character described, the combination of a paper carriage, numeral keys controlling said carriage, means actuated by the operation of the numeral keys and connected to said carriage for vertically computing a group of independent columns of figures concomitantly as the same are written, and supplementary mechanism for simultaneously cross computing the successive lines forming the group of said vertical columns, and mechanism for actuating the two computing mechanisms in unison either in the same or in opposite directions.

98. In an apparatus of the character described, the combination of a carriage, numeral keys controlling said carriage, means actuated by the operation of the numeral keys and connected to said carriage, for writing a plurality of independent columns of figures, means for horizontally computing the rows of said columns of figures, and means for simultaneously computing the vertical totals of said columns, said means comprising mechanism for actuating the two computing means in unison either in the same or opposite directions.

99. In an apparatus of the character described, the combination of a carriage, numeral keys controlling said carriage, means actuated by the operation of the numeral keys and connected to said carriage for printing columns of figures, means actuated by said numeral keys for horizontally computing the rows of figures of said columns, and means for computing the totals of said columns, each of said means comprising computing mechanism and an individual actuator for said computing mechanism, said actuators being capable of being rotated in unison either in the same or in opposite directions.

100. In an apparatus of the character described, the combination of a carriage, numeral keys controlling said carriage, means actuated by the operation of the numeral keys and connected to said carriage for printing columns of figures, means actuated by said numeral keys for horizontally computing the rows of figures of said columns, and means for computing the rows of figures of said columns, each of said means comprising computing mechanism and an individual actuator for said computing mechanism, either actuator being operated independently of the other.

101. In an apparatus of the character described, the combination of two computing mechanisms, independent actuators for said mechanisms, means for rotating said actuators in unison in the same direction, means for rotating said actuators in unison in opposite directions, and means for selectively bringing into operation either of the aforesaid means.

102. In an apparatus of the character described, the combination of two computing mechanisms, independent actuators for said mechanisms, numeral keys, means operated by the numeral keys for actuating one of said actuators, and selectively operable connections between the actuators, whereby the second actuator may be operated in unison with the first, either in the same or in the reverse direction.

103. In an apparatus of the character described, the combination of means for writing a series of independent columns of figures, a main computing mechanism for ver-

tically computing the said columns, supplementary computing mechanism for computing said figures horizontally, means controlled by the operation of numeral keys for performing both of said computations, and means actuated simultaneously with the actuation of a portion of said main computing mechanism in one direction for actuating said supplementary computing mechanism in the other direction, whereby said latter mechanism can then be set to zero while its total is being added by the operator to the previous total so obtained.

104. In an apparatus of the character described, the combination of means for writing a series of independent columns of figures, main computing mechanism suitably grouped for obtaining the individual totals of said columns, supplementary computing mechanism for obtaining the cross totals of said figures in rows, an operative connection between said main and supplementary computing mechanisms, whereby they can rotate in unison in either direction, a paper carriage, numeral keys, means controlled by the operation of said keys for advancing said carriage and for actuating said main and supplementary computing mechanisms, and means for changing said operative connection whereby the supplementary mechanism can operate in the reverse direction to the main computing mechanism.

105. In a combined typewriting and adding machine, the combination with a carriage of a typewriting machine, types, and keys to operate the types and control the carriage, of a series of computing wheels forming part of the computing mechanism, a master wheel to turn said computing wheels, a constantly revolving motor having yieldable means to turn said master wheel, an escapement wheel to control said master wheel, means to enable said keys to control the action of said escapement wheel, and means for effecting relative step-by-step movement between said master wheel and said computing wheels.

106. In a combined typewriting and adding machine, the combination with a carriage of a typewriting machine, types, and keys to operate the types and control the carriage, of a primary element comprising a series of computing wheels forming part of the computing mechanism, a second primary element comprising a master wheel to turn said computing wheels, a constantly revolving motor having yieldable means to turn said master wheel, an escapement wheel to control said master wheel, means to enable said keys to control the action of said escapement wheel, said primary elements being relatively movable, and means to connect one of said primary elements to said carriage for effecting such relative movement.

107. In a computing machine, the combination with a key-controlled drive shaft, of a plurality of computing heads each having a master wheel shaft connected to said drive shaft, and means to enable said drive shaft to turn one of said master wheel shafts in either direction independently of another of said shafts.
108. In a computing machine, the combination with a key-controlled drive shaft, of a plurality of computing heads each having a master wheel shaft connected to said drive shaft, and means to enable said drive shaft to turn certain of said master wheel shafts in either direction and simultaneously turn certain of the remaining master wheel shafts in the opposite direction.
109. The combination with a computing head, of a master wheel therefor, a series of numeral keys, a constantly rotating motor yieldably connected to said master wheel, and numeral key-controlled valuating mechanism for determining the extent of actuation of said master wheel by said motor.
110. The combination with a computing head, of a series of numeral keys, a constantly rotating motor, numeral key-controlled valuating mechanism for determining the extent of actuation of certain parts of said computing head by said motor, and a connection between said motor and said computing head enabling said certain parts of said computing head to remain passive while said motor is rotating.
111. The combination with a computing head, of a source of power, a master wheel driven thereby for actuating certain parts of said computing head to accumulate a calculation, means for controlling the actuation of said certain parts by said source of power, and connections enabling the activity of said source of power while said master wheel remains passive.
112. The combination with a computing head, of a valuating or indexing wheel for determining the extent of actuation of certain parts of said computing head, a series of numeral keys, and numeral key-controlled mechanism for coöperating with said valuating wheel, said valuating wheel comprising a body portion having a series of openings therein, stop bolts or index pins slidably mounted in said openings and capable of occupying a plurality of positions, each of said stop bolts having a groove therein corresponding to each position, and spring means for engaging said grooves to secure said stop bolts in their several positions of adjustment.
113. The combination with a computing head, of a valuating wheel for determining the extent of actuation of certain parts of said computing head, a series of numeral keys, and numeral key-controlled mechanism for coöperating with said valuating wheel comprising a body portion, a series of openings therein, stop bolts movably mounted in said openings so as to occupy a plurality of positions relative thereto, each of said stop bolts having a plurality of grooves therein corresponding to the several positions of adjustment, and a spring encircling said body portion capable of engaging in said grooves in all of said stop bolts to hold said stop bolts in any of their adjusted positions.
114. The combination with a main computing head, of a supplementary computing head, numeral keys for determining the action of said computing heads, mechanism for enabling said main computing head to carry on a plurality of different types of computation, and mechanism for enabling said supplementary computing head to simultaneously carry on the same or a different type of computation as that of said main computing head with the same numbers.
115. In a computing attachment for a typewriter, having a case-shift key, the combination of a series of numeral keys, computing mechanism, individual means respectively attached to said numeral keys but detachable therefrom, operative connections between said individual means and the computing mechanism whereby the operation of each of said means variably actuates said computing mechanism, means actuated with the operation of the case-shift key for simultaneously disconnecting all of the numeral keys from said individual means, and an independent device for additionally controlling the connections of said numeral keys with the individual means simultaneously.
116. In a computing attachment for a typewriter having a case-shift key, the combination of a series of numeral keys, computing mechanism, individual means for respectively connecting said numeral keys with the computing mechanism, a longitudinal bar for simultaneously moving all of said individual means into and out of operative engagement, and means for moving said bar by the operation of the case-shift key.
117. In a computing attachment for a typewriter having a case-shift key, the combination of numeral keys, computing mechanism, operative connections between the numeral keys and the computing mechanism, means actuated by the depression of the case-shift key for controlling said operative connections, an independent device for additionally controlling such connections, and a spring arranged to oppose the movement of said device away from either of its limiting positions.
118. In a computing attachment for a typewriter having a case-shift key, the com-

- combination of numeral keys, computing mechanism, operative connections between the numeral keys and the computing mechanism, means actuated by the depression of the case-
5 shift key for releasing said operative connections, an independent device for releasing such connections, a spring arranged to oppose the movement of said device away from either of its limiting positions, and a
10 second independent device for again normally connecting them.
119. In an apparatus of the character described, the combination of computing mechanisms, each performing different selective computations, an actuator for each, means whereby the actuators may be operated in unison in either direction, and means whereby either can be operated in either direction independently of the other.
120. In an apparatus of the character described, the combination of main and secondary computing mechanisms each performing different selective computations, an actuator for each, means for operating said actuators in unison in either the same or reverse direction, and means whereby either actuator can be actuated independently of the other in either direction.
121. The combination with a computing typewriter having figure type keys, of a key to disconnect the adding machine from the figure type keys, a key to effect reconnection thereof, and means to maintain temporarily either the connection or the disconnection.
122. The combination with a succession of computing wheels, of a tens-carrying device controlled by one wheel to effect advance of the next higher wheel, and a constantly rotated member to engage said tens-carrying device and actuate the same.
123. The combination with a series of tens-carrying devices, of a constantly rotating member common to said series to engage any thereof and actuate the same.
124. The combination with a succession of computing wheels, of a tens-carrying device controlled by one wheel to effect advance of the next higher wheel, and a power-rotated member to engage said tens-carrying device and actuate the same, each tens-carrying device being rotatable by the wheel of lower denomination, and being forced into engagement with the power-rotated member to be rotated thereby, the tens-carrying device having teeth to engage said rotating member, the latter having a yielding construction and gripping each tooth to turn the tens-carrying device.
125. The combination with a succession of computing wheels, of a tens-carrying device controlled by one wheel to effect advance of the next higher wheel, each tens-carrying device being rotatable by the wheel of lower denomination, and a power-rotated yielding cylinder normally occupying a position between adjacent teeth of the tens-carrying device, to be engaged thereby.
126. The combination with a succession of computing wheels, of a tens-carrying device controlled by one wheel to effect advance of the next higher wheel, each tens-carrying device being rotatable by the wheel of lower denomination, and a power-rotated yielding cylinder normally occupying a position between adjacent teeth on the tens-carrying device to be engaged thereby, the tens-carrying device having teeth to engage the wheel of higher denomination and also teeth to be engaged by a single tooth on the wheel of lower denomination.
127. The combination of two sets of computing wheels, each set having tens-carrying devices, two constantly revolving members for driving said wheels, a common driving shaft for said constantly revolving members, and independent devices for reversing the rotation of said constantly revolving members respectively.
128. The combination of two sets of computing wheels, each set having tens-carrying devices, two constantly revolving members, for driving said wheels, a common driving shaft for said constantly revolving members, independent devices for reversing the rotation of said constantly revolving members, and reversing levers also controlling the means for reversing the direction of rotation of the computing wheels.
129. The combination with primary mechanism for adding numbers written in each of a plurality of primary columns so as to produce the footing of each individual column separately from the others, of mechanism for simultaneously computing the cross footing of all the numbers written in the several columns on each line across the page, and automatically computing the sum of all of such cross footings and reversing means for the cross footing device.
130. In an apparatus of the character described, the combination of main computing mechanism performing a certain selective computation, and secondary computing mechanisms performing a different selective computation, an independent actuator for each, and means independent of the position of said computing mechanisms for operating said actuators in unison either in the same or in the reverse direction.
131. The combination with mechanism including computing wheels for adding numbers written in each of a plurality of primary columns so as to produce the footing of each individual column separately from the others, of secondary mechanism including computing wheels for simultaneously computing the cross footing of all the num-

- bers written in the several columns respectively on each line across the page, and automatically computing the sum of all of such cross-footings, and clutch connections 5 permitting the independent reverse driving of the computing wheels of one of said mechanisms with respect to the other.
132. The combination of a prime mover, with a key-operated escapement controlling 10 the same, a cross computing device, a master wheel for actuating the same driven by said prime mover, primary computing devices, and a master wheel for actuating the same also driven by said prime mover.
133. The combination of a prime mover, a key-operated escapement controlling the same, a cross computing device, a cross master wheel for actuating the same, a cross master wheel shaft carrying said cross master wheel, primary computing devices, a primary master wheel for actuating the same, a single shaft driven by said motor, a gearing connecting the same to drive said primary master wheel, and means for driving 25 said cross master wheel shaft also by said motor.
134. The combination of a prime mover and a key-operated escapement controlling the same, a cross computing device, primary 30 computing devices, a primary master wheel for driving the same respectively, a single power-driven shaft, a primary master wheel shaft carrying said primary master wheel and driven from said driven shaft, a cross 35 master wheel shaft to carry the same master wheel of said cross computing device, and a clutch for enabling the said primary master wheel shaft to revolve in either direction.
135. The combination of a prime mover, a key-operated escapement therefor, a cross computing device, a cross master wheel actuating the same, primary computing devices, a primary master wheel for actuating the same, a single power-driven shaft, a primary master wheel shaft carrying said primary master wheel, and driven by said power-driven shaft, a cross master wheel shaft carrying said cross master wheel, a 40 lever, and a clutch operated thereby for causing the cross master wheel shaft to revolve in either direction.
136. The combination of a prime mover, a key-operated escapement therefor, a cross 45 computing device, a master wheel mechanism for actuating the same, primary computing devices, and a primary master wheel mechanism for actuating the same, one of said master wheel mechanisms being arranged to be entirely disconnected from said prime mover, while the other master wheel mechanism continues to operate.
137. The combination of a prime mover, a key-operated escapement controlling the 50 same, a cross computing device, a cross master wheel mechanism for actuating the same, primary computing devices, and a primary master wheel mechanism for actuating the same, said master wheel mechanisms being independently disconnectible from said prime mover.
138. The combination of a prime mover, a key-operated escapement therefor, a cross computing device, a cross master wheel mechanism for actuating the same, primary 55 computing devices, a primary master wheel mechanism for actuating the same, a single power driven shaft, a primary master wheel shaft driven thereby and carrying said primary master wheel, a cross master wheel shaft carrying said cross master wheel, and also driven from said driven shaft, a clutch for causing the said primary master wheel shaft to revolve in either direction, a lever for operating the same, and means for entirely disconnecting the master wheel shaft 60 from said prime mover.
139. The combination of a primary computing mechanism, a secondary computing mechanism, a primary master wheel for 65 driving said primary computing mechanism, a secondary master wheel for driving said secondary mechanism, constantly rotating tens-carrying members co-operating with said mechanisms, two pairs of clutches 70 for controlling the wheels and tens-carrying members, and a single lever controlling each 75 pair of said clutches.
140. The combination with a typewriting mechanism having a series of numeral keys 80 capable of causing the writing of both numbers and other characters, and a shifting means enabling the change between numbers and other characters as written by the striking of said numeral keys, of a computing mechanism including connections to 85 said keys whereby said keys when controlling the writing of numbers can also control a concomitant actuation of said computing mechanism, and means operated by said 90 shifting means for disconnecting said computing mechanism from said keys at said keys, whereby said keys will be entirely free from the drag of said computing mechanism 95 while writing other characters than numbers.
141. The combination with a plurality of individual computing mechanisms, each capable of carrying on individual computations, of actuators individual to each computing mechanism, and means independent 100 of the position of said computing mechanisms whereby said actuators may be operated in unison either in the same or in opposite directions.
142. The combination with a typewriting mechanism including numeral keys, of a computing mechanism having a rotatable 105

element, a motor for rotating said element, key-controlled locking means for preventing the rotation of said element by said motor, and a slip or loose connection to said motor 5 enabling the rotation of said motor while said locking means is in action.

143. The combination with a digit wheel and master wheel mechanism, of a rotary controller or indexing wheel connected to 10 the master wheel, a motor for driving the master wheel to the extent permitted by said controller, a slip connection being provided between said motor and the master wheel, a series of settable indexing devices on said

15 controller, numeral keys, means mounted on the machine frame and connected with said numeral keys for setting said indexing devices, a pinion rotatable by the set indexing devices, an escapement wheel connected to 20 said pinion, means under the control of the keys for permitting said escapement wheel to be advanced by said controller, and means for subsequently restoring the set indexing devices to normal positions.

25 144. The combination with two totalizers, of a master wheel for each of said totalizers, a carriage to produce relative movement between the totalizers and the master wheels simultaneously, keys to control the extent of 30 rotation of the master wheels in unison, and shiftable means to perform either addition or subtraction upon either totalizer while either addition or subtraction is being performed upon the other totalizer.

35 145. The combination with two totalizers, of a master wheel for each of said totalizers, a carriage to produce relative movement between the totalizers and the master wheels simultaneously, keys to control the extent of 40 rotation of the master wheels in unison, and shiftable means to cause either master wheel to either add, subtract or be neutral while the other master wheel either adds or subtracts.

45 146. The combination with two totalizers having a tandem arrangement, of a master wheel for each of said totalizers, a carriage to produce relative movements between the totalizers and the master wheels simultaneously, shafts for said master wheels, keys to control the extent of rotation of the master 50 wheels in unison, a shaft connecting said shafts, and shiftable means connected to said connecting shaft to cause said master 55 wheels to perform either simultaneous addition or simultaneous subtraction upon said totalizers.

147. The combination with two totalizers having a tandem arrangement, of a master 60 wheel for each of said totalizers, a carriage to produce relative movements between the totalizers and the master wheels simultaneously, shafts for said master wheels, keys to control the extent of rotation of the master

wheels in unison, a shaft connecting said 65 shafts, and shiftable means connected to said connecting shaft to control the activity of each master wheel independently of the other.

148. The combination of two totalizers 70 having a tandem arrangement and fixed together, a master wheel for each totalizer, means for effecting relative movements between the master wheels and the totalizers, means for moving the master wheels in 75 unison, and key-controlled devices for controlling the rotation of the master wheels in unison.

149. The combination of a plurality of totalizers having a tandem arrangement, master wheels for said totalizers, a carriage for producing relative movement between the master wheels and the totalizers, a cross-shaft to connect said master wheels, a source of power to drive said cross-shaft in a single direction only, whereby said master 85 wheels are driven in unison, a key mechanism to control the extent of rotation of said cross-shaft, and shiftable means for reversing at will the direction of the rotation of either of said master wheels effected by said cross-shaft, independently of the other master wheel.

150. The combination of a plurality of totalizers having a tandem arrangement, master wheels for said totalizers, a carriage for producing relative movement between the master wheels and the totalizers, a cross-shaft to connect said master wheels, a source of power to drive said cross-shaft in a single direction only, whereby said master 95 wheels are driven in unison, a key mechanism to control the extent of rotation of said cross-shaft, and shiftable means between said cross-shaft and said master wheels for 100 controlling the activity of each master wheel independently of the other.

151. The combination of a plurality of totalizers having a tandem arrangement, master wheels for said totalizers, a carriage for 110 producing relative movement between the master wheels and the totalizers, a cross-shaft to connect said master wheels, a source of power to drive said cross-shaft in a single direction only, whereby said master wheels 115 are driven in unison, a key mechanism to control the extent of rotation of said cross-shaft, and shiftable means between said cross-shaft and said master wheels for controlling both the activity and direction of 120 each master wheel independently of the other.

152. The combination of a plurality of totalizers, master wheels for said totalizers, a carriage for producing relative movement 125 between the master wheels and the totalizers, a drive shaft common to said totalizers, keys, means under the control of the keys to

drive said shaft in a single direction only, and shiftable means between said drive shaft and said master wheels for controlling the activity of each master wheel independently of the other.

153. The combination of a plurality of totalizers, master wheels for said totalizers, a carriage for producing relative movement between the master wheels and the totalizers, a drive shaft common to said totalizers, keys, means under the control of the keys to drive said shaft in a single direction only, and shiftable means between said drive shaft and one of said master wheels for controlling its direction of movement independently of the other master wheel.

154. The combination with a main totalizer, of a cross totalizer, means to enable cross computation to be performed upon the cross totalizer of separate numbers run up on the main totalizer at successive portions of the length thereof, and means shiftable at will to control the character of computation performed upon said totalizers.

155. The combination with a main totalizer, of a cross totalizer, means to enable cross computation to be performed upon the cross totalizer of separate numbers run up on the main totalizer at successive portions of the length thereof, and means shiftable at will to control the character of computation performed upon one of said totalizers independently of the other.

156. The combination of a main totalizer, a cross totalizer, means, inclusive of master wheel devices connected to turn in unison and a carriage, to enable cross computation to be performed upon the cross totalizer of separate numbers run up on the main totalizer at successive portions of the length thereof, and means to control the direction of rotation and activity of either master wheel device independently of the other.

157. The combination of a main totalizer, a cross totalizer, means, inclusive of master wheel devices connected to turn in unison and a carriage, to enable cross computation to be performed upon the cross totalizer of separate numbers run up on the main totalizer at successive portions of the length thereof, said totalizers having a tandem arrangement, and a common driver for said master wheel devices.

158. The combination of a main totalizer, a cross totalizer, means, inclusive of master wheel shafts connected to turn in unison and a carriage, to enable cross computation to be performed upon the cross totalizer of separate numbers run up on the main totalizer at successive portions of the length thereof, and connections shiftable at will between said shafts for controlling their activity and direction of rotation.

159. The combination of keys, a series of

digit wheels, a master wheel to be controlled by the keys, a key-controlled carriage for effecting relative movement between the master wheel and the digit wheels, a source of power, and carry-over mechanism for said digit wheels, including initiating devices operable by the digit wheels, and also including actuating means connected directly to said source of power to be driven thereby; said carry-over mechanism connected to operate simultaneously with said master wheel.

160. The combination of keys, a series of digit wheels, a master wheel to be controlled by the keys, a key-controlled carriage for effecting relative movement between the master wheel and the digit wheels, a source of power, carry-over mechanism for said digit wheels, including initiating devices operable by the digit wheels, and also including actuating means connected directly to said source of power to be driven thereby; said carry-over mechanism connected to operate simultaneously with said master wheel, and shiftable means for reversing the action of said digit wheels and said power-driven actuating means.

161. The combination of a series of digit wheels, a master wheel therefor, means for enabling the master wheel to drive the digit wheels *seriatim*, carry-over devices whose movements are initiated by the digit wheels, a revolute driving device extending along the carry-over devices and having means to act thereon to insure the completion of the operation of said carry-over devices, and means for simultaneously reversing the direction of said master wheel and said driving device.

162. The combination of a series of digit wheels, a master wheel therefor, means for enabling the master wheel to drive the digit wheels *seriatim*, carry-over devices whose movements are initiated by the digit wheels, a revolute driver extending along the pinions to act thereon to insure the completion of the rotative movements thereof, said revolute driver being in the form of a yielding roll: and a source of power connected to said roll to drive the same.

163. The combination of a plurality of totalizers having digit wheels, master wheels for said totalizers, means for enabling the master wheels to act in unison each to drive its digit wheels *seriatim*, carry-over devices whose movements are initiated by the digit wheels, and continuously revolute drivers extending along said carry-over devices to act thereon to insure the completion of the operations thereof.

164. The combination of a plurality of totalizers having digit wheels, master wheels for said totalizers, means for enabling the master wheels to act in unison each to drive

- its digit wheels *seriatim*, a motor by which the master wheels are driven, carry-over devices whose movements are initiated by the digit wheels, and yielding revolute drivers 5 driven by said motor independently of said master wheels and extending along said carry-over devices to act thereon and insure the completion of the operations thereof.
165. The combination of a plurality of totalizers having digit wheels, master wheels for said totalizers, means for enabling the master wheels to act in unison each to drive its digit wheels *seriatim*, a motor by which the master wheels are driven, carry-over devices whose movements are initiated by the digit wheels, revolute drivers driven by said motor independently of said master wheels and extending along said carry-over devices to act thereon and insure the completion of the operations thereof, and means for controlling the activity and direction of each master wheel with its associated carry-over driver independently of the other master wheel and its associated carry-over driver.
166. The combination of a short array of digit wheels, a succession of master wheels for engaging said wheels one at a time to perform cross computation, a long array of 30 digit wheels, a single master wheel whereby the wheels in said long array may be operated in unison with the operation of the digit wheels in said short array, by said succession of master wheels, and means for effecting relative movement between the master wheels and the digit wheels.
167. The combination of a short array of digit wheels, a succession of master wheels for engaging said wheels one at a time to perform cross computation, a long array of 40 digit wheels, a single master wheel whereby the wheels in said long array may be operated in unison with the operation of the digit wheels in said short array by said succession of master wheels, and means for effecting relative movement between the master wheels and the digit wheels, and for controlling the activity and direction of the master wheels.
168. The combination of a step-by-step feeding carriage, a plurality of computing heads, a plurality of actuating shafts for said computing heads, and shiftable means for causing either shaft either to turn in addition direction or to turn in subtraction direction, or to remain neutral, while the other shaft either adds, subtracts, or remains neutral.
169. The combination of a step-by-step moving carriage, a plurality of computing heads, a shaft having a master wheel for one of said computing heads, a counter-shaft parallel with said shaft and having a master wheel for the other of said computing heads,
- said computing heads having a tandem arrangement so that each is out of range of the master wheel of the other, and means for rotating said shafts in unison.
170. The combination of a step-by-step moving carriage, a plurality of computing heads, a shaft having a master wheel for one of said computing heads, a counter-shaft parallel with said shaft and having a master wheel for the other of said computing heads, said computing heads having a tandem arrangement so that each is out of range of the master wheel of the other, means for rotating said shafts in unison, and shiftable means for securing the performance of either simultaneous addition or simultaneous subtraction on said computing heads.
171. In a combined typewriting and computing machine, the combination with a typewriter carriage, of a plurality of computing heads for computing simultaneously in a computing zone, the extent of the computing zone in which it is possible for a single simultaneous computation to take place being but a very small fraction of the full stroke of said typewriter carriage, 90 master wheels for said computing heads, one wheel for each head, said typewriter carriage having means to cause relative movements between the computing heads and the master wheels, each computing head 95 being, at all points in the travel of said carriage, beyond the range of the master wheel belonging to the other computing head; and means for causing said master wheels either to add in unison or subtract 100 in unison.
172. In a combined typewriting and computing machine, the combination with a typewriter carriage, of a plurality of computing heads for computing simultaneously in a computing zone, the extent of the computing zone in which it is possible for a single simultaneous computation to take place being but a very small fraction of the full stroke of said typewriter carriage, 105 master wheels for said computing heads, one wheel for each head, said typewriter carriage having means to cause relative movements between the computing heads and the master wheels, each computing head being, 110 at all points in the travel of said carriage, beyond the range of the master wheel belonging to the other computing head; and means for causing either master wheel to either add or subtract, while the other 120 master wheel either adds or subtracts.
173. In a combined typewriting and computing machine, the combination with a typewriter carriage, of a plurality of computing heads for computing simultaneously in a computing zone, the extent of the computing zone in which it is possible for a single simultaneous computation to take

place being but a very small fraction of the full stroke of said typewriter carriage, master wheels for said computing heads, one wheel for each head, said typewriter carriage having means to cause relative movements between the computing heads and the master wheels, each computing head being, at all points in the travel of said carriage, beyond the range of the master wheel belonging to the other computing head; and means for causing either master wheel either to add, subtract, or remain neutral, while the other master wheel either adds, subtracts, or remains neutral.

174. In a combined typewriting and computing machine, the combination of numeral keys, a plurality of totalizers, individual master wheels for said totalizers, means, including a driving device, for connecting said keys to said master wheels to operate them in unison, manually shiftable devices between said driver and said master wheels, for silencing either master wheel while the other rotates, and means, independent of said manually shiftable devices, for disconnecting said keys from the master wheels; whereby the adjustment of said manually shiftable devices may be preserved during the temporary disconnection of the numeral keys from the master wheels.

175. In a combined typewriting and computing machine, the combination of numeral keys, a plurality of totalizers, individual master wheels for said totalizers, means connecting said keys to said master wheels to operate them in unison, shiftable means for reversing the direction of either master wheel independently of the other, and means independent of said shiftable means, for disconnecting said keys from the master wheels.

176. In a combined typewriting and computing machine, the combination of numeral keys, a plurality of totalizers, individual master wheels for said totalizers, means connecting said keys to said master wheels to operate them in unison, shiftable means for controlling the direction and activity of each master wheel independently of the other, and means independent of said shiftable means, for disconnecting said keys from the master wheels.

177. The combination with digit wheels, of a master wheel, numeral keys, means to operate the master wheel at the operation of the keys, said digit wheels having means for initiating the carry-over operations, and means distinct from the digit wheels for assisting or completing each carry-over operation; means being provided for driving said assisting means both during and subsequent to the operation of the digit wheel which initiates the carry-over operation.

178. The combination with digit wheels, of a master wheel, numeral keys, a motor

mechanism for driving the master wheel at the operation of said keys, said digit wheels having means for initiating the carry-over operations, and means operated by said motor mechanism for assisting or completing each carry-over operation, said motor being effective to drive said assisting means both during and subsequent to the operation of the digit wheel which initiates the carry-over operation.

179. The combination of a series of digit wheels, a master wheel, carry-over trains whose movements are initiated by the digit wheels, an assisting device common to the carry-over trains for completing each carry-over operation immediately upon the same being initiated by the digit wheel, and a single finger-piece having means for reversing the operation of both said master wheel and said assisting device.

180. In a combined typewriting and computing machine, the combination with numeral keys and a carriage controlled thereby, of a main computing mechanism having the capacity of a plurality of computing zones, a cross-computing mechanism comprising a set of computing wheels, means for operating the cross-computing mechanism simultaneously with the main computing mechanism in each zone to an extent determined by the keys, and shiftable means for setting the main computing mechanism to subtraction in any zone independently of the cross-computing mechanism.

181. In a combined typewriting and computing machine, the combination with numeral keys and a carriage controlled thereby, of a main computing mechanism having the capacity of a plurality of computing zones, a cross-computing mechanism comprising a set of computing wheels, means for operating the cross-computing mechanism simultaneously with the main computing mechanism in each zone to an extent determined by the keys, and means for either setting the main computing mechanism to subtraction or silencing the same in any zone independently of the cross-computing mechanism.

182. In a combined typewriting and computing machine, the combination with numeral keys and a carriage controlled thereby, of a main computing mechanism having the capacity of a plurality of computing zones, a cross-computing mechanism comprising a set of computing wheels, means for operating the cross-computing mechanism simultaneously with the main computing mechanism in each zone to an extent determined by the keys, and means for controlling the activity and direction of operation of each computing mechanism independently of the other.

183. In a combined typewriting and computing machine, the combination with nu-

- meral keys and a carriage controlled thereby, of a main computing mechanism having the capacity of a plurality of computing zones, a cross-computing mechanism comprising a set of computing wheels, means for operating the cross-computing mechanism simultaneously with the main computing mechanism in each zone to an extent determined by the keys, manually shiftable means for controlling the direction of operation of said main computing mechanism in any zone, and other manually operable means for controlling the direction of operation of the cross-computing mechanism in any zone.
184. In a combined typewriting and computing mechanism, the combination with a carriage movable through a succession of computing zones, of a main totalizing mechanism having the capacity of a plurality of zones, and including an element connected to said carriage to be advanced thereby, a cross totalizing-mechanism, means to enable the cross-totalizing mechanism to compute the numbers carried into the main totalizing mechanism in a single run of the carriage, and shiftable means to set said cross-totalizing mechanism to subtraction independently of the main totalizing mechanism when the latter is computing in any zone.
185. In a combined typewriting and computing mechanism, the combination with a carriage movable through a succession of computing zones, of a main totalizing mechanism having the capacity of a plurality of zones, and including an element connected to said carriage to be advanced thereby, a cross-totalizing mechanism, means to enable the cross-totalizing mechanism to compute the numbers carried into the main totalizing mechanism in a single run of the carriage, and shiftable means for either setting said cross-totalizing mechanism to subtraction or silencing the same independently of the main totalizing mechanism when the latter is operating in any zone.
186. In a combined typewriting and computing mechanism, the combination with a carriage movable through a succession of computing zones, of a main totalizing mechanism having the capacity of a plurality of zones, and including an element connected to said carriage to be advanced thereby, a cross-totalizing mechanism, means to enable the cross-totalizing mechanism to compute the numbers carried into the main totalizing mechanism in a single run of the carriage, and means to control the activity of each of said mechanisms independently of the other.
187. In a combined typewriting and computing mechanism, the combination with a carriage movable through a succession of computing zones, of a main totalizing mechanism having the capacity of a plurality of zones,

and including an element connected to said carriage to be advanced thereby, a cross-totalizing mechanism, means to enable the cross-totalizing mechanism to compute the numbers carried into the main totalizing mechanism in a single run of the carriage, and means to control the activity and direction of operation of each of said totalizing mechanisms independently of the other.

188. In a calculating machine; accumulating means; a primary master wheel; an auxiliary master wheel; and means connecting the two whereby the auxiliary master wheel may be caused 1, to rotate in the same direction as the primary master wheel, 2, not rotate at all, and 3, to rotate in the opposite direction from the primary master wheel.

189. In a calculating machine the combination of a primary master wheel, an auxiliary master wheel, a set of numeral keys operatively connected with both master wheels, and means adapted to be placed in any one of three positions and thereby determining that (1) the action of any one of the numeral keys rotates the auxiliary master wheel in the same direction as the primary master wheel, (2) not at all, or (3) in the opposite direction from the primary master wheel.

190. In a calculating machine; accumulating means; a primary master wheel; an auxiliary master wheel; hand-operable means adapted to be located in various settings; a mechanism connecting said second means and the master wheels, the locating of said means in one setting causing the two master wheels to rotate in the same direction, the locating of said second means in another setting causing one master wheel to rotate and the other master wheel to remain stationary, and the locating of said second means in a third setting causing the master wheels to rotate in opposite directions.

191. In a calculating machine; accumulating means; a primary master wheel; an auxiliary master wheel; and mechanism connecting the two whereby the auxiliary master wheel may be caused to rotate in the same direction, not to rotate at all, or to rotate in the opposite direction from the primary master wheel, and whereby the directions of rotation of both the primary master wheel and the auxiliary master wheel may be reversed.

192. In a calculating machine, accumulating means; a master wheel shaft; a master wheel revoluble therewith; shifting means capable of being shifted to several settings; gearing connected with said shifting means; an auxiliary master wheel; the gearing on the shifting means being adapted to cooperate with both the primary and the auxiliary master wheels whereby the primary master wheel and the auxiliary master wheel rotate

in the same direction, when the shifting means is in one of its settings, and rotate in opposite directions when the shifting means is in a second of its settings, and whereby one master wheel rotates and the other master wheel does not rotate when the shifting means is in a third setting.

193. In a calculating machine, accumulating means; a master wheel shaft; a master wheel revoluble therewith; shifting means capable of being shifted to several settings, gearing connected with said shifting means; an auxiliary master wheel; the gearing on the shifting means being adapted to coöperate with both the primary and the auxiliary master wheels whereby the primary master wheel and the auxiliary master wheel rotate in the same direction when the shifting means is in one of its settings, and rotate in opposite directions when the shifting means is in a second setting, and whereby one master wheel rotates and the other master wheel does not rotate, when the shifting means is in a third setting; and hand-operable means connected to the shifting means.

194. In a calculating machine; accumulating means; a primary master means and an

auxiliary master means for operating said accumulating means; mechanism for driving both; and disconnecting mechanism for disconnecting the auxiliary master means from the driving mechanism whereby the primary master means may be operated without simultaneously operating the auxiliary master means.

195. In a calculating machine; accumulating means; primary master means and an auxiliary master means for operating said accumulating means; and mechanism for driving both, said mechanism including shifting means adapted to control the operation of the auxiliary master means and locatable into several settings, the auxiliary master means and said shifting means co-operating while said shifting means is in either of two of its settings, but not co-operating while said shifting means is in a third setting.

In testimony whereof I have hereunto set my hand in the presence of two subscribing witnesses.

WALTER WRIGHT.
